UNITED STATES PATENT OFFICE.

WILLIAM NICHOLS MEARS, OF BROOKLINE, MASSACHUSETTS, ASSIGNOR TO AMERICAN ROTARY MOTOR COMPANY, OF BOSTON, MASSACHUSETTS, A CORPORATION OF MAINE.

ROTARY ENGINE.

1,152,535.

Specification of Letters Patent. Patented Sept. 7, 1915.

Application filed December 19, 1907. Serial No. 407,235.

To all whom it may concern:

Be it known that I, WILLIAM NICHOLS MEARS, a citizen of the United States, residing at Brookline, in the county of Norfolk and State of Massachusetts, have invented an Improvement in Rotary Engines, of which the following description, in connection with the accompanying drawings, is a specification, like letters on the drawings representing like parts.

This invention relates to rotary compressors and engines, preferably of the internal combustion type, wherein I may employ any suitable agent or agents. If a non-explosive agent or agents be employed, I may utilize steam, air or other fluid under pressure; and if an explosive mixture or mixtures be employed, I may utilize any suitable agents, as, for example, an explosive mixture of air and alcohol, or air and gasoline, or air and kerosene, or gas and in fact any suitable hydro-carbon or other agent, which, when mixed with air or other suitable fluid, produces an explosive mixture. If desired, any suitable gas or other substance, whether fluid or non-fluid, may be employed, which when ignited produces an explosion that may be utilized in the production of rotary motion, or a continuously burning gas may be employed to be used alone or to be mixed with other agents of any suitable nature. I also contemplate the utilization of a plurality of explosive mixtures or substances, as, for example, alcohol and air or ethylene gas and air, it being apparent, however, that if a plurality of explosive substances or mixtures be employed, I may utilize an explosive agent. In the practice of my invention, the explosive substances, when of a fluid nature, are preferably supplied under pressure.

In order that the principles of my invention may be clearly understood, I have disclosed a single type or embodiment thereof in the accompanying drawings, wherein—

Figure 1 is a top plan view of a rotary engine preferably of an explosive type embodying one form of my invention; Fig. 2 is a front elevation of the engine represented in Fig. 1; Fig. 3 is a left hand side elevation thereof; Fig. 4 is a central, longitudinal, horizontal section of the engine represented in Fig. 1; Fig. 5 is a vertical,

central, transverse section thereof; Fig. 6 is a central, longitudinal, vertical section thereof; Fig. 7 is a longitudinal section on the irregular line 7—7 of Fig. 5; Fig. 8 is an enlarged detail of portions of the rotor abutment controlling means representing the parts in their forward operating position; Fig. 9 is a view similar to Fig. 8 but representing the corresponding parts in their forward neutral position; Fig. 10 is a detail, partly in vertical, transverse section and partly in elevation, of one of the heads of the engine and representing one manner of means for introducing a temperature regulating agent and an explosive agent; Fig. 11 is a perspective view, partially broken away, of a form of bearing adapted to be interposed between the shaft and one or both of the heads of a reversible engine, and from which the motive agent or agents may be introduced into the rotor; Fig. 12 is a similar view of such bearing, but representing a modified manner of introducing a plurality of motive agents into the rotor; Figs. 13 and 14 are views similar to Figs. 11 and 12 respectively, but representing a form of bearing particularly intended for use in connection with one way engines; Fig. 15 is an enlarged detail representing in transverse cross section the portion of the casing wherein the rotor is mounted, and one of the abutments in operative relation thereto, the parts being in the position assumed at the time of explosion, the rotor being shown in elevation; Fig. 16 is a similar detail but representing the position assumed by the parts as the exterior valve for admitting the motive agent or agents through the casing is opening and representing the scavenging of the explosion chamber and the passages within the rotor, the rotor being shown in section; Fig. 17 is a perspective view of the strip or holder with which the abutment or abutments may be provided; Fig. 18 is a perspective view of the shoe that may be used in connection with said strip or holder; Fig. 19 is a sectional detail representing one manner of means for taking up wear between the heads and the rotor, and representing also the manner in which wear may be taken up between the bearings and the rotor and representing packing and oiling means for the

abutment. Fig. 20 is a transverse section taken through the rotor and one of the abutments upon the line 20—20 of Fig. 15, and showing packing means and means for supplying a lubricant to the parts; Fig. 21 is a substantially vertical section of an abutment upon the line 21—21 of Fig. 15. Fig. 21^a is a perspective detail representing a tongue and groove connection for members 10 of the packing represented in Fig. 21; Fig. 22 is a detail perspective view of a portion of an abutment, and representing more particularly means for supplying a lubricant; Fig. 23 is a vertical section upon the line 23—23 of Fig. 20; Fig. 24 is a sectional detail upon the line 24—24 of Fig. 8 and representing yielding means for maintaining engagement of the abutment and rotor; Fig. 25 is a rear face view taken upon the irregular line 25—25 of Fig. 24 and looking in the direction of the arrow in said figure; Fig. 26 is an enlarged longitudinal section representing the cam employed for opening the valve admitting the motive agent or agents through the casing; Fig. 27 is a side elevation of the construction shown in Fig. 26 and representing two valve operating cams; Fig. 28 is a sectional detail upon the line 28—28 of Fig. 29 and representing 30 means for varying the control of the admission of a motive agent or agents through the rotor; Fig. 29 is a detail in plan of the construction shown in Fig. 28; Fig. 30 is a vertical section upon the line 30—30 of Fig. 35 4 and representing means for controlling the cams for admitting the motive agent or agents through the casing; Fig. 31 is a vertical transverse section of a one way engine wherein my invention may be embodied; Fig. 32 is a longitudinal vertical sectional detail taken through the abutment represented in Fig. 31; Fig. 33 is a transverse vertical section taken through one of the spools represented in Fig. 4 for imparting movement 45 to the rotor cam with respect to the rotor; Fig. 34 is a vertical sectional detail upon the line 34—34 of Fig. 35 and representing the rotor cam and connections for imparting the described relative movement thereto; Fig. 35 is a longitudinal vertical section upon the line 35—35 of Fig. 8 and representing the connections between the spool and the rotor cam; Fig. 36 is a longitudinal sectional view, partially in elevation, 50 upon the irregular line 36—36 in Fig. 8 and representing the same parts; Figs. 37 to 44 inclusive represent details in transverse section of means for imparting movement to the radial arm and radial guide 55 represented in Fig. 8 as operatively connected to the abutment, said figures representing the position successively assumed in reversing the engine; Fig. 45 is an enlarged sectional view of a motive agent admission 60 passage, showing screening means therein;

and Fig. 46 is a diagrammatic view upon a reduced scale showing the manner of supplying the temperature regulating agent.

Referring more particularly to the single type or embodiment of my invention herein 70 illustrated, the engine herein represented is provided with a casing and an internal member, herein for convenience of description termed a rotor. In the practice of my invention, I impart a relative rotary movement to the casing and rotor. Movement of rotation may be imparted to either the casing or the rotor. In the present type of the invention, however, I have represented the rotor as mounted for rotation within 80 the casing, which herein is stationary.

The casing wherein the rotor is mounted may be of any suitable outline in cross section, being either circular or non-circular, as is found best adapted to the particular requirements of the type of engine wherein my invention is employed. Referring more particularly to Figs. 4, 5 and 6, the casing, which herein is represented as substantially circular in cross section and as stationary, 90 is represented at 1, it being adapted to receive therein for rotary motion a shaft 2 mounted in suitable bearings 3, represented most clearly in Figs. 4 and 6. Mounted within the casing 1 upon the shaft 2 is a 95 rotor 4 of any suitable type, and inclosing the rotor within the casing are provided suitable heads 5 and 6, both of which are preferably removable from the casing 1. While in the specification and claims I refer 100 to one or more heads, it is to be understood that one of the heads may be integral with or form a portion of the casing, and the claims are to be construed in view of this statement.

While I may secure the heads 5 and 6 to the casing 1 in any suitable manner and may construct the heads in the form that is found most desirable, herein (see Fig. 6) I extend a portion 7 of each head into the casing 1 at 110 opposite sides thereof, it being apparent that a portion or the whole of either or both heads may be received within the casing. In the present type of the invention, however, I have represented each of the heads 115 as having a portion extending into the casing and an encircling rim 8 adapted to be positioned adjacent the ends of the casing. The portions 7 of the heads should, to secure the best results, be tightly fitted within the 120 casing where contacting with the inner face of the casing. While either or both of the rims 8, which for the best results should be continuous, may be tightly fitted against the opposing ends of the casing 1, preferably 125 and as most clearly represented in Figs. 4, 6 and 7 I so construct one or both of the heads as to permit the taking up of wear between the head and the rotor and the part or parts associated with the latter. While 130

this may be accomplished in any desired manner, preferably I provide bolts 9 (see Fig. 19) passing through the rim 8 of each head and tapped into the ends of the casing 1, whereby said rims may be drawn into the desired relation with respect to the casing, the rims 8 of the said heads being, when the parts are assembled, preferably spaced somewhat from the adjacent ends of the casing 1, the extent of which spacing may be determined in any suitable manner, as, for example, by the provision of means limiting the movement of the said rims of the head toward the ends of the casing. To that end, 15 in Figs. 10 and 19, I have represented set screws 10 tapped into the rims 8 with their inner ends projecting beyond the inner faces of said rims and into contact with the ends of the casing or other part positioned there- 20 against. If desired, a gasket or the like 12 may be introduced between the ends of the casing 1 and the rims 8, with which the limiting screws 10 may contact. It is ap- 25 parent that by adjusting the screws 10 as desired I may determine the extent of in- 30ward movement of the rims 8 of the heads toward the casing 1. Not only do the set screws tend to limit the inward movement of the rims but they act to hold the said rims in their predetermined position.

I contemplate the provision of means whereby I may position the rotor with respect to the casing and also the provision of means for taking up wear between the rotor and the heads of the casing while providing a tight joint between them. This may be accomplished in any desired manner. In the present type of the invention, I provide an inwardly projecting surface or surfaces that may be formed integral with the head or heads of the casing or operatively connected thereto in any suitable manner. Such inwardly projecting surface or surfaces may be of any desired shape, being formed by the revolution of a straight, irregular or curved line about an axis, and thus being of desired cylindrical form or of any other suitable formation. In the present embodiment of the invention, I show such inwardly projecting surfaces as tapering and specifically as frusto-conical in form. Referring more specifically to Figs. 4, 6 and 7 and also to Figs. 11 to 14, it will be observed that the bearings 3—3 for the shaft 2 are so formed upon their inner faces as to provide frusto-conical surfaces 11 adapted to engage similar faces upon and to present a wide bearing contact to the rotor 4 mounted for rotation within the casing 1. 55 If desired, any suitable form of bearing, as, for example, ball or roller bearings may be employed between the bearings 3 and the shaft 2. While the bearings 3 may be formed integrally with the heads 5 and 6, preferably they are formed separately there-

from and are received within approximately central openings 13 formed in said heads 5 and 6. Herein I connect the said bearings to the heads by suitable screw threaded bolts 14 passed through the rim 15 upon said bearings and tapped into the adjacent portion of the heads 5 and 6. The rims 15 may be suitably spaced from the head to permit the taking up of wear between the conical surface and the rotor, and to that end I may employ means such as described for taking up wear and to provide packing between the heads and the casing, employing if desired limiting and holding set screws and a gasket such as shown at 12 or any other device ac- 80 complishing this end. It is apparent that the construction of parts may be reversed and that the tapering portion may be formed upon or connected to one or both end faces of the rotor, to be received within a corre- 85 spondingly recessed portion of each head or heads.

While each bearing 3, if formed separately from the heads 5 and 6, may be integrally formed by casting or otherwise, preferably 90 each of said bearings is formed of a plurality of parts, since in this type of the invention I contemplate providing a chamber or chambers within each bearing for the introduction of the motive agent or agents, which 95 chambers may be more readily provided by forming said bearings of a plurality of parts. Inasmuch as I contemplate, if de- 100 sired, the introduction of a plurality of different motive agents through said bearings, I suitably form a corresponding num- 105 ber of chambers. To that end, I herein pro- 110 vide an inner sleeve like member 16 serving as the bearing proper for the shaft 2, the inner end thereof being frusto conical in 105 shape, as previously described, each bearing in cross section being of a general T-shape to provide for the reception thereon of the secondary member 17, between which and the inner sleeve is provided the chamber or 110 chambers referred to. Preferably the sleeve 16 is screw threaded, as represented at 18 and 19, to receive thereon the secondary member 17. In any suitable manner within the bearing or bearings 3 I provide one or 115 more chambers for a motive agent or agents, which may be of any suitable nature as previously stated. Preferably, however, and in this form of the invention, I provide a main chamber 20 in each bearing which for 120 convenience of construction is provided be- 125 tween the sleeve 16 and the secondary mem- ber 17. While any suitable motive agent may be introduced into this chamber, I herein contemplate the introduction of air, preferably under suitable pressure, or, if the motive agents are mixed outside of the engine, a suitable mixture of air and some explosive agent. The air or a mixture, if de- 130 sired, is introduced into each chamber 20

(see Fig. 10) by means of one or more pipes 21 communicating with any suitable source of supply. If a plurality of chambers be provided in each bearing, I may suitably dispose them as desired. Herein (see Figs. 5 4, 11 and 12) I have represented a chamber 22 also formed between adjacent faces of the sleeve 16 and secondary member 17, and preferably of smaller area than the chamber 10 20. Any suitable motive agent may be introduced into the chamber 22. If desired, one or more chambers in addition to the chamber 22 may be provided in either or both bearings 3 for the introduction of other motive agents in any similar manner. As illustrated in Fig. 10, I provide a suitable pipe 23 for the introduction of a motive agent 15 into the chamber 22.

In case a plurality of chambers be formed 20 in each bearing 3, the agents introduced therein may be conducted therefrom into the rotor in any suitable manner, either independently of each other or commingled in any manner. By the provision of means, 25 as previously described, for taking up wear between the heads and the rotor, and if desired between the bearings and the rotor, I am enabled to secure a tight adjustable and running fit between the part or parts in the 30 rotor into which the motive agent or agents are introduced and the intermediate port or ports, whether provided in the bearings or in the heads themselves, it being apparent that instead of introducing one or more of 35 the agents through the bearings, they may be introduced in any suitable manner through the heads themselves.

The manner of introduction of the motive 40 agent or agents into the rotor depends upon the speed of the engine and the nature of the motive agent or agents introduced, in some cases it being preferable to mix a plurality of agents prior to their introduction into the rotor and in other cases it being desirable to mix 45 them within the rotor. It is apparent furthermore that if a plurality of agents be employed, I may mix certain of them prior to their introduction into the rotor and may further mix the same or other agents within 50 the rotor. To this end, any suitable construction may be provided. I contemplate the provision of means for introducing a motive agent from the chamber 22 in such manner that it may mix with the agent introduced 55 into the chamber 20 after the admission of such latter agent to the rotor, and I also contemplate introducing the second motive agent from any suitable source directly into the rotor. Viewing more particularly Fig. 11, I have therein represented a passage 23' leading from the chamber 22 and discharging into the rotor, preferably closely adjacent the point of discharge from the chamber 20 into the rotor, so that the 60 second motive agent may be sprayed by that

issuing from the chamber 20. In Fig. 12, I have illustrated a construction whereby the second motive agent may be mixed with the first motive agent prior to the admission of the latter into the rotor, and also whereby 70 such second motive agent, or a portion thereof if desired, may be introduced directly into the rotor, there to be sprayed by the first motive agent. In such construction, the second motive agent is introduced 75 by means of a passage 24, by which it is directed to a valve chamber wherein is located a valve 24^a, leading from which are the separate passages 24^b and 24^c, the former leading directly into the rotor as represented at 24^d 80 and the latter having preferably a plurality of inwardly directed ports 24^e which may be discharged directly into the chamber 20 or at some point in advance thereof but anterior to the rotor passages. Herein, I have 85 represented the chamber 20 as provided at its forward portion with an inwardly projecting annular lip 25, wherein are formed the parts 24^f, an automatic check valve 25^a being located in advance of the admixture 90 of the first and second motive agents to prevent back firing. It is apparent, however, that such valve may be provided at any suitable point. If the check valve be located as shown, it serves to control the admission of 95 the first agent from the chamber 20 and also of the second agent through the passage 24^e. The valve 24^a has suitable passages formed therein, whereby communication may be established between the passage 24 and either 100 the passage 24^b or 24^c or both simultaneously, whereby the second motive agent may be introduced directly into the rotor and also so as to be mixed with the first motive agent before the latter enters the rotor. It 105 is apparent furthermore that the valve 24^a serves to regulate the amount of the supply of the motive agent or agents through either the passages 24^b or 24^c or both. It is apparent that the construction may be such 110 that a third motive agent may be introduced through the chamber 24^b, in which case different agents may be introduced through the chambers 24^b and 24^c respectively. Preferably, the agent admitted directly from the 115 chamber 22 shown in Fig. 11 or by means of the passage 24^b in Fig. 12, into the rotor is introduced into the latter in a stream or streams at a suitable angle to the agent or agents introduced from the chamber 20, as 120 clearly illustrated in Figs. 11 and 12. It will furthermore be apparent, viewing Fig. 12, that the agent introduced through the chamber 24^c is introduced at such an angle 125 with respect to the agent introduced through the chamber 20 as to be sprayed or comminuted into fine particles thereby. Furthermore, as represented in Fig. 7, the adjacent portion 29 of the inlet in the rotor is 130 so formed as to provide a surface 30 to re-

ceive the impact of the incoming agent or agents, whereby they are deflected therefrom and more thoroughly diffused before their passage through the rotor. Any suitable number of outlets from the chamber 20 to the rotor may be provided. While I may employ a single outlet, preferably I employ two outlets arranged at substantially diametrically opposite points. If the engine 10 be a reversible one, as it is in certain forms of my invention, I provide a number of inlets from the chamber 20 corresponding to the requirements of the engine in such case. It will be apparent that if the engine be a 15 reversible one, I preferably provide eight inlets from the chamber 20, preferably only four of them being operable in either direction of rotation.

I contemplate the provision of means for 20 controlling the introduction of the motive agent or agents into the rotor. Not only may I employ means for varying or regulating in any desired manner the introduction of the motive agent or agents however 25 introduced into the rotor, but, if the engine be of the reversible type, I preferably provide means whereby when the engine is operative in one direction one or more of the motive agent inlets may be closed in whole 30 or in part, and whereby when the engine is operative in the opposite direction the inlet or inlets previously closed may be opened in whole or in part. While such valve or 35 valves may be positioned as required depending upon the type of engine employed in that specific form of the invention herein illustrated, I have represented a valve 31 (Figs. 6, 7 and 11) mounted upon the inclined inner face of each bearing 3 and suitably connected to operating means therfor. 40 Herein, each ring is represented as secured by screws 32 to an annulus 33 mounted upon the sleeve 16 and provided with suitable gear teeth 34, in order that it may be operated in a manner to be more fully described, either 45 merely to vary or regulate the introduction of the motive agent or agents or to provide for the operation of the engine in either direction. It will be apparent that the 50 valve will be positioned between the head and the rotor and upon either part, depending upon the requirements of the particular engine. Each valve 31 is provided with a suitable opening or openings to control the 55 admission of the motive agent. In the type of the invention herein disclosed, I provide preferably a plurality of openings 32 to control the two pairs of substantially diametrically opposed openings from the chamber 20 and also one or more openings 33' to control the passages leading directly from the chamber or chambers 22. The ring or 60 rings 31 constitute also packing rings positioned between the head or heads and rotor. Such packing function may exist wholly in-

dependently of the valve function of such ring or rings.

In order to permit variation in the point or points at which the motive agent or agents is or are introduced through the tapering bearing or bearing 3 into the rotor, I contemplate the provision of means for imparting a movement of partial rotation to one or both of said tapering bearings. While this may be accomplished in any suitable 75 manner, in Figs. 10 and 11 I have represented one of the tapering bearings as provided with elongated slots 34^a to receive the bolts 14, whereby the bearing is positioned. Radially extending from the head is a lug 80 34, with opposite faces whereof engage set screws 34^b, by suitably adjusting which the circumferential position of the tapering bearing may be varied, as found desirable, the bolts 14 being loosened preparatory to 85 such adjustment and tightened thereafter. It is apparent that either head with its tapering bearing may simultaneously have imparted thereto in unison the described movement of partial rotation to accomplish this 90 same result. It is furthermore apparent that, if the tapering portion or portions be provided on the rotor to extend into similarly recessed portions upon the head or heads of the bearings, the same movement of 95 partial rotation may be imparted to the head or heads of the bearings.

In certain types of engines, I find it desirable to introduce a motive agent or agents into the interior of the casing 1 otherwise 100 than by the described inlet passages through the rotor. While this may be accomplished in any suitable manner, preferably I form the casing 1 with one or more passages 105 therein intermediate the heads 5 and 6. Referring more particularly to Figs. 5 and 7, the casing 1 is provided preferably at substantially diametrically opposite points with projecting portions 35 adapted to be connected with the source of supply of any 110 suitable motive agent. If the engine be of the reversible type, I contemplate the provision of a suitable motive agent or agents otherwise than through the opening or 115 openings provided in the projection or projections 35, and to that end have provided one or more, and herein a pair of substantially opposed projections 36—36, through which the agent or agents will be introduced when the engine is operating in the reverse 120 direction. Preferably, each opening 36 is arranged at about 90° from each opening 35.

Any suitable motive agent or agents may be introduced from any desired source into the pipe or pipes 37, from whence it is 125 directed by means of pipes 38—38 and 39—39 into the passages within the projecting portions 35—35 and 36—36 respectively. I may provide suitable check valves 40 controlling the introduction of the motive agent 130

or agents to prevent back firing. In connection with each check valve 40, I may provide, as shown in Figs. 1 and 3, a suitable safety valve 41 preferably opposed thereto, as represented.

5 While any suitable motive agent may be introduced through the inlet passage or passages 37, preferably and in this type of the invention I introduce thereto compressed air. I may introduce another motive agent 10 or agents to be discharged into the casing 1 otherwise than through the rotor and intermix it or them, if desired, with the compressed air or other agent introduced 15 through the passage or passages 37. If such additional motive agent be introduced, I may provide (see Fig. 5) a suitable inlet pipe 42 leading from any suitable source of supply and communicating by means of the 20 pipe or pipes 43 with the casing, as, for example, adjacent the projections 35-35 and 36-36, or may deliver the same so that it may be intermixed with the agent introduced through the passage or passages 37 25 outside the casing. If desired, the pipes 42 or 43 may be provided with suitable check or other valves, such as represented at 44-44.

It is apparent that I may introduce any 30 desired number of motive agents, as, for example, three or four, into each combustion chamber, if a plurality thereof be employed, and one or more of such agents may be introduced either into each combustion chamber 35 or into an anterior mixing chamber preferably provided in connection therewith. In case I introduce one motive agent through an inlet pipe 38 and a second motive agent through an inlet pipe 43, each of said 40 agents may be introduced unmixed with each other into the interior of the casing 1, or they may be suitably intermixed at any point. In advance of the check valve 40, I provide preferably a check valve 45, in advance of which I preferably provide a mixing chamber 46, the check valve 45 then 45 preferably acting also as a mixing valve. At the outlet of the mixing chamber 46 I provide a suitable valve 47, which, if the 50 agent or agents be introduced under pressure, may act as a safety valve and as a balanced valve. The motive agent introduced through the passage 38 passes directly past the check valve 45 into the mixing chamber 55 46. The motive agent introduced through the pipe 43 may be discharged into the mixing chamber 46 and preferably in such manner that the discharge thereof is controlled by a check valve, which may be the check 60 valve 45 controlling the admission of the motive agent through the inlet pipe 38. To that end, in this type of the invention, I provide an annular chamber 48 communicating with the pipe 43, and lead therefrom 65 preferably a plurality of inwardly directed

passages 49 herein represented as discharging preferably at right angles to the inflow of the motive agent from the pipe 38 and if desired at the seat of the valve 45. Preferably the motive agent is introduced from the 70 pipe 43 in such a manner that it may be sprayed or comminuted into fine particles by the incoming rush of the motive agent introduced from the pipe 38. If desired, I may also introduce motive agents from the 75 pipe 43 at a point operatively in advance of the passages 49, as, for example, directly into a combustion chamber of the engine. While this may be accomplished in any desired manner, I have herein represented a 80 passage 50 leading from the pipe 43 and communicating with an annular passage 51, leading from which are preferably a plurality of passages 52 discharging at any suitable point into the combustion chamber 85 53, but herein at the point whereat the valve 47 is seated. Preferably the passage or passages 52 are so disposed as to introduce the motive agent at a suitable angle, preferably at a right angle to the other inflowing agent 90 or agents likewise controlled by said valve 47. The valve 47 is provided upon some portion opposite the head thereof with a shouldered portion 47' which is of larger 95 diameter than that portion of the head of the valve against which the incoming agent or agents may impinge when the valve is closed. In this manner, the valve acts as a differential valve, the pressure of the incoming agent or agents tending therefore to 100 keep said valve seated. The diameter of the shouldered portion 47' in this embodiment of the invention is such that the pressure tending to keep the valve closed only very slightly exceeds that tending to open the 105 same. In some types of my invention the diameter of the shouldered portion 47' may be so slight that in practical operation the valve 47 acts as a balanced valve. It will be apparent that the motive agent introduced by means of the passage 50 will be sprayed or comminuted into fine particles by the incoming rush of the agent or agents from the mixing chamber 46 into the combustion chamber 53. If desired, I may provide a suitable valve or valves controlling 110 the admission of the motive fluid from the pipe 43. To that end, I have herein provided a valve 54 (see also end elevation in Fig. 2) having a suitable opening or openings therein permitting the introduction of a motive agent from said pipe 43, either into the chamber 48 or into the passage 50 or into both simultaneously, or whereby the admission of such motive agent may be entirely or 115 partially cut off. Any suitable type of valve may be employed controlling the discharge of the motive agent or agents into the combustion chamber 53. While herein I have represented a valve of the conical 120 125 130 135

type, I may employ a flat mushroom or other valve. In either type of valves, the motive agent introduced through the passage 50 may in its passage impact upon the valve 47 and be thereby thoroughly broken up into fine particles. The check valve 45 may likewise be of any suitable type, as, for example, a flat mushroom or other valve receiving the impact of the incoming agent or agents.

10 The contour and extent of that portion of the combustion chamber 53, into which the motive agent or agents is first introduced may be as desired. Preferably, however, I form such portion of the chamber of relatively small extent in the direction of the incoming current of the motive agent or agents, so that such agent or agents may impact against a wall or walls of such combustion chamber, and herein against the opposing wall 55. While the extent of that portion of the combustion chamber 53 that is adjacent the valve 47 may be as desired longitudinally of the engine, preferably at this point it but slightly exceeds the diameter of the valve 47, thus permitting the explosive agent or agents to be admitted into the combustion chamber throughout the circumferential extent of said valve 47, thus thoroughly scavenging that portion of the chamber by driving in advance of it the burnt gases remaining from the previous discharge. It is apparent that the valve 47 may be disposed as desired. For example, it may be arranged longitudinally of the casing 1, or at any suitable angle thereto, so as to introduce the motive agent or agents in any desired manner into the combustion chamber 53.

That portion of each combustion chamber 40 that is radially beyond the utmost limit of the rotor in the circumferential movement of the same may be of any desired extent and configuration. Preferably, however, that portion of said chamber intermediate 45 the valve 47 and the utmost radial limit of the rotor is substantially of a flattened or more or less bell shape, the walls 56 and 57 of said chamber not only diverging when viewed in cross section transversely of the longitudinal extent of the casing, but also preferably diverging when viewed in cross section longitudinally of the casing, as most clearly represented in Fig. 7. That is to say, the walls of said chamber preferably 50 flare outwardly in every direction, but in this type of the invention flare more longitudinally of the casing than transversely thereof. Preferably, however, the wall 57 is flared or cut away to a greater extent 55 than is the wall 56 in a direction transverse of the casing. In the rotation of the rotor 4, as, for example, in the direction of the arrow adjacent thereto in Figs. 5 and 16, preferably the valves 45 and 47 are opened 60 just prior to the engagement of the surface

of the rotor with the wall 57 of the combustion chamber, thereby permitting the incoming agent or agents to scavenge the combustion chamber by expelling the burnt gases of the preceding ignition between the rotor 70 and the casing to the exhaust. It will be apparent that for a suitable period after the contact of the rotor with the wall 57 of the combustion chamber, the valves 45 and 47 remain open. In Fig. 5, the said valves are 75 represented as closed, in order most clearly to represent the preferred mechanical means for operating said valve. It is to be understood, however, that at this period of operation, said valves 45 and 47 are open, one of 80 said valves being so represented in Fig. 16. The walls 56 and 57 of the combustion chamber merge into the preferably concentric portion of the interior of the casing 1 at any suitable point, as, for example, at the points 85 58 and 59. Preferably the distance between the points 58 and 59 is of somewhat less extent than the greatest extent in cross section of that portion of the rotor that is sufficiently radially removed from the center 90 thereof to contact with said walls 56 and 57 at the point at which they merge with the inner concentric face of the casing 1. In this manner, after the contact of the rotor with the wall 57 at 59, that portion of the 95 combustion chamber 53 anterior to the rotor when in such position, remains closed from the remaining portion of the combustion chamber for a greater period of time than is necessary for any given point upon the 100 rotor to travel from the point 58 to the point 59, thereby permitting the pressure of the incoming agent or agents within such confined portion of the combustion chamber 53 to equalize the pressure of said agent or 105 agents within the mixing chamber 46 and to permit the burning of the mixture before the main chamber 53 is opened up. Substantially at the time when the pressure of the agent or agents within such confined 110 portion of a combustion chamber has reached the point described, the outer surface of the rotor 4, in its onward travel in the direction of the arrow represented in Fig. 5, becomes separated from the point 58 115 of the wall 56, owing to the contour of said rotor, to be more fully described, thereby permitting the compressed agent or agents to be admitted into that portion of the casing that lies radially inside of the points 58 120 and 59, wherein is formed a main combustion chamber defined radially by the outer surface of the rotor and the casing and circumferentially of the rotor by the contacting portion of said rotor and the casing in 125 a forward direction and in a rearward direction in any suitable manner, as by any suitable abutment that may be provided within the casing or upon the rotor to contact with the rotor or with the wall of the casing 130.

This main combustion chamber when first opened permits the least possible expansion of the motive fluid in the extension of such combustion or working chamber which is 5 radially beyond the points 58, 59, and which extension I herein term the ignition chamber. In the present type of the invention, I employ an abutment 60 mounted in the casing and adapted to contact with the surface 10 of the rotor 4, thereby, as represented most clearly in Fig. 15, defining the rearward limit of said main combustion chamber 53.

The rotor 4 is provided with suitable passages therein to receive the motive agent or 15 agents introduced through the head or heads or through the bearing or bearings 3. Since preferably I introduce an agent or agents through each bearing 3, I provide (see Fig. 20 7) two pairs of oppositely directed passages 62 and 63 leading from the points of introduction of the agent or agents through each bearing 3, and thence extending to the periphery of the rotor in any desired manner, it being apparent that one half of the 25 passages, are employed when the engine is operative in one direction, the remaining passages being employed when the engine is operative in the opposite direction as represented in Fig. 7. If I mix a plurality of 30 motive agents introduced into the rotor, then preferably each passage 62, 63 is provided with the impact receiving surface or surfaces 30. If, however, only a single motive agent is introduced through either head or bearing 35 into the rotor, the passages 62 and 63 need not be provided with such impact receiving surface or surfaces 30. It will be apparent that the passages 62—62 and 63—63 may be and preferably are so constructed as to introduce the agent or agents near opposite 40 ends of the rotor, it being apparent, however, that they may be introduced at any desired point. It will be apparent that the introduction of the motive agent or agents 45 through the passages 62—62 and 63—63 in the rotor and also from the mixing chambers 53 produces a very thorough admixture of the agent or agents within the casing. One or more of the passages 62 or 63 may 50 be cut away at the periphery of the rotor and at the wall of the passage opposing the leading or casing abutting wall thereof, as represented at 64 in Fig. 16, whereby the leading wall of such passage or passages 55 presents an unobstructed shoulder to receive the impact of the motive agent. It will be apparent that the passages in the rotor that are employed when the engine is reversed have an opposite formation to accomplish 60 the same result.

While the shape of the rotor 4 in cross section may be such as is desired, preferably (see Fig. 5) it is of a general elliptical form. In the present type of the invention, 65 the peripheral surface thereof is provided

with oppositely disposed portions 65 and 66 concentric with the center of rotation thereof and cut by the shorter axis thereof. At peripheral points intermediate the concentric portions 65 and 66 and so disposed as to be cut by the longer axis of the rotor, I also preferably provide concentric portions 67 and 68. The peripheral extent of each concentric portion 65, 66, 67 and 68 may be such as is found desirable. Preferably, however, the concentric portions 67 and 68 are of somewhat greater extent than the distance between the points where the walls 57 and 58 merge into the concentric surface of the casing. The peripheral extent of the concentric portions 65 and 66 is preferably such that at the moment of explosion, in such specific type of my invention employing an explosive agent or agents, the abutments 60 are in contact with such concentric portions 85 and are therefore at rest, having reached the inward limit of their radial movement, said concentric portions 65 and 66 being sufficiently prolonged to permit the abutment to remain in engagement with the concentric 90 portions until all or a large portion of the motive agent or agents have expended the bulk of their energy. It being understood that I may employ steam or other non-explosive agent or agents, the extent of the concentric portion 65 and 66 is such that when the bulk of the load of the motive agent or agents of any character is against the face of the abutment or abutments 60, such abutments are at their inward point 100 of radial movement and are therefore stationary. The portions of the peripheral face of the rotor intermediate the concentric portions 65, 67, 66 and 68 may be of any preferred contour and extent. Preferably, 105 however, the terminal portions of such intermediate portions merge so gradually into the adjacent concentric portions that when the abutments are in engagement with such terminal portions, in either direction of rotation of the rotor, there is the minimum amount of radial movement of said abutments. In this manner, as a concentric portion of the rotor passes from beneath the engaging face of the abutment, such abutment receives first a very slight radial movement which increases in extent to a maximum point, and thereafter so diminishes that, when the other terminal of the intermediate portion comes beneath the abutment, the extent of radial movement thereof is gradually reduced to a minimum. In other words, each abutment or abutments passes gradually from a state of rest to its condition of maximum radial movement and again gradually approaches a state of rest. 115

If desired, I may provide suitable packing to be interposed between the rotor and the casing or the heads thereof. In Figs. 4, 5, 6, 7, 15 and 16, I have represented 130

suitable packing strips, which may be of the general construction illustrated in my co-pending application, Serial No. 397,788, filed Oct. 17, 1907. As shown in Fig. 5, I 5 provide one or more packing strips 69 adapted to be received in recessed portions of the concentric portions 67 and 68 of the rotor, which strips may extend from one end face of the rotor to the other or through 10 any desired dimension of the rotor. Packing may also be interposed between one or both end faces of the rotor and the heads of the casing. While the packing may be provided in either the rotor or the casing 15 head or heads, herein I have represented each head as recessed, as represented at 70, in which are disposed annular metallic packing strips 71 and 72, preferably of the general character illustrated in the said co-pending application. If desired, the packing strips 71 or 72 may be extended outwardly so as to connect with the packing strip or strips 69.

The abutment or abutments provided in 25 this type of my invention are preferably mounted in the casing for movement radially to the axis of rotation of the rotor. Referring more particularly to Figs. 4 and 5, each abutment 60 is provided at the opposite ends with circular portions 73 and 74, adapted to be received within the bearing rings 103 mounted in correspondingly shaped openings in the heads 5 and 6, the construction being such as to permit each 35 abutment to rock upon an axis parallel to the shaft 2. The portions 73, 74 constitute trunnions which are herein shown as cylindrical, but which may be of any desired shape in longitudinal section. Each abutment should be snugly received within the part wherein it is mounted for rotation, and to that end, if desired, I may interpose suitable packing carried either by the abutment or by the part wherein it is mounted. 40 Herein I have represented the peripheral face of each abutment as annularly recessed, as represented at 76, wherein I dispose one or more packing strips, preferably in the form of split rings. Herein I provide a 45 packing ring 77, the opposite edge faces whereof preferably incline outwardly and also provide a packing strip in the form of a split ring 78, the edge thereof contacting with one of the edges of the split ring 77, being correspondingly inclined, the opposite 50 edge being less inclined in the same direction and engaging a correspondingly inclined side wall of the recess 76. With such construction of parts the tendency of 55 the split ring 77 is to expand outwardly, and also to move toward the rotor, such tendencies being augmented by the tendency of the split ring 78 to expand outwardly; thus wedging the split ring 77 so as to make 60 a tight fit at the inner portion of the bearing contact between the rotor and the ring 75. The inclination of the outer face of the recess 76 is such as to prevent a free inward movement of the split ring 78; thus assisting the wedging action of said split ring upon the ring 77. If desired, suitable oiling openings may be provided in one or more of said split rings. That portion 79 of each abutment embraced between the inner faces of the heads 5 and 6, as represented most clearly in Figs. 4, 5, 20 and 21 75 is of reduced extent in a direction radially of the rotor but in a direction transversely thereto is of greater extent than the diameter of the bearing wherein the said abutment is mounted. Preferably each portion 79 is provided with means permitting the exhaust of the motive agent or agents therethrough. To that end I may provide one or more openings therein. In the type of 80 my invention illustrated in said figures, I represent a single opening 80, arranged at midlength of said portion 79. As represented in Fig. 5, the contour of the inner face of the portion 79 of each abutment is 85 such that the rotor 4 contacts with said abutment or abutments only at or adjacent opposite edges thereof, the portion intermediate such edges being sufficiently radially removed from the center of rotation 90 of the rotor to be out of contact with the said rotor. The end disk-like portions of the rotor upon which the same is trunnioned, being of less diameter than the portion or web 79 of the abutment, each end 95 portion 79' contacts with that portion of the head partially surrounding the trunnion, a tight fit being established between such portions of the head and the abutment web 79. That is to say, the adjacent faces 100 of said heads and web 79 are flush and contact throughout the movement of the abutment. The outer edges of the web 79 of each abutment are of such contour as to be 105 snugly received within the casing, which in the preferred type of my invention (see Fig. 5) is provided with a recessed portion 110 concentric with the axis of rotation of each abutment, the said outer edges of the abutments being in this case correspondingly 115 convexed to fit therein. If desired, wearing strips, as represented at 81, (Figs. 5 and 21) may be provided in recessed portions of the said recessed portion of the casing. If desired, packing strips may be interposed 120 between the casing and the abutments. Herein I have represented as each abutment as provided with recesses 82 on its opposite edges within which are mounted one or more packing and oiling strips 83 of 125 any suitable construction. If desired, packing or oiling means may be provided along that face of each web of the abutment that contacts with the head.

If desired, the portion or portions of each 130

abutment that contacts with the rotor, may be formed integrally with such abutment. Preferably, however, and in order to permit the removal thereof, if worn, and for other purposes, I provide a detachable portion, which I mount upon each portion of the abutment that contacts with the rotor. Herein (see Figs. 5, 17 and 18) I have represented each abutment as provided near opposite edges of its inner face with a dovetailed portion 84, within which is received a strip or holder 85 of suitable wear resisting material. While the rotor may contact directly with the portion of the main web of the abutment or of the holder or strip 85, preferably I mount in the latter an oscillatory shoe 86. To that end I suitably concave or recess the inner face of the strip or holder as represented at 87 longitudinally thereof and, if desired, provide transverse holding recesses 88, which may be under-cut upon one or both sides, if desired. Within the recessed portion 87 is received for oscillation the correspondingly convexed face 89 of the shoe, having projecting therefrom transversely extending tongues 90, to be received within the holding recesses 88 and being under-cut upon one or both edges, if desired. In the reversible type embodying my invention, as illustrated in Fig. 5, when the engine is operated in either direction, one of the shoes 86 is removed from contact with the rotor. To retain such shoe in operative relation to its holder when in such position, I provide any suitable holding means. Herein I have provided a screw 91, mounted in said shoe and having a preferably reduced portion 92 thereof extending into a slot 93 formed in the strip or holder 85, the construction being such that when such shoe is withdrawn from operative engagement with the rotor, the screw engages the walls of said slot, retaining the screw and holder in operative relation. Each shoe 86 is so formed as to provide two lines of contact between the shoe and the rotor throughout the period of contact of such shoe with the rotor. To that end, I have longitudinally recessed or channeled each shoe, as represented at 94, leaving the opposing rims 95, 95 providing the separated lines of contact referred to. By providing the separated lines of contact a tighter joint is made between the abutment and the rotor, thus preventing the escape of the motive agent at such points. Preferably I provide for oiling the inner concaved face 87 of the strip or holder 85 and the inner face of the shoe 86. Herein I provide between the main or web portion of each abutment and each holder 85 an oil groove, herein represented at 96, in the holder. Leading therefrom are a suitable number of oiling channels 97, extending to the inner concaved face of the holder 85, which is

preferably provided with a longitudinally disposed channel or channels 98. If desired, I may provide channels for conducting the oil to the recesses 88. Any suitable means may be provided to lead the oil from the holder to the inner face of the corresponding shoe. Herein I provide a suitable number of oiling channels 99, transversely disposed with respect to the oiling channel 98 and at corresponding points in the shoe 86 I provide oiling passages 100 and 101, the outer ends whereof register throughout the oscillation of the shoe with the transverse grooves 99. The inner end of the oiling passage 100 terminates at the inner face of the rim 95 and the oiling passage 101 preferably terminates in the groove 94 and herein in adjacent the opposite rim 95. Preferably and viewing Figs. 5, 17 and 18, that rim 95 to which the oil is led directly, is that rim with which the peripheral face of the rotor first engages, it being understood, however that any desired oiling means may be provided. By the described construction, however, it will be apparent that the peripheral surface of the rotor first engages an oiled rim 95 and then an oiled channel 94. In this manner the shoe 86 acts as an oiled packing strip, effectively preventing the escape of the motive agent. If desired, I may make the transverse oiling channels 99 of such restricted linear extent that oil will not be supplied at all times to the channels 100 and 101, thus preventing the oil from being forced back through the holder or strip at the time of explosion, if this character of agent be employed.

I may employ other means than that described for maintaining a suitable fit between the outer face of each web 79 of each abutment and the parts contacting therewith. Instead of having such portion of each web 79 contact with the head, as represented at 85, I may provide (see Figs. 21 and 22) a split collar 102, the outer face whereof may contact throughout more or less of its extent with the adjacent face of the web 79, the outer face of such split collar being outwardly beveled, as represented, and receiving thereagainst a correspondingly shaped face of a split bearing 103, the rear preferably beveled end whereof is engaged by the correspondingly shaped face of a sleeve 104, that may be provided with screw threads to be received in any suitable part of the head. If desired, one or more of the parts, as, for example, the split bearing 103 may be provided with an oil channel or channels. The construction of the split collar 102 is such that it tends at all times to establish a tight fit between it and the outer face of the web 79 and take up wear occurring therebetween, the split bearing 103 tending to establish a tight fit between itself

and the bearing for the trunnions of the abutments.

Any suitable means may be employed for supplying a lubricant to the abutment or abutments. In Figs. 20 to 23 inclusive, I have represented means for supplying oil under pressure to the bearings of the abutment and contacting portions thereof. Any suitable lubricant, such as oil, may be introduced through passages 103^a formed in the heads 5 and 6 (see Fig. 20) leading to an annular chamber or reservoir 103^b formed between the split bearing 103 and the respective head. The oil may be delivered from said reservoir by radial passages 103^c formed in the split bearing 103 to an annular chamber 103^d that may be formed between the split bearing 103 and the ring packing ring 77, if the latter be employed. In the construction herein specifically shown, the packing ring 77 is provided with preferably a plurality of radial passages 103^e whereby the lubricant may be delivered to a secondary reservoir or chamber 103^f, which is prolonged as represented in Fig. 21 and which supplies oil to the face of the abutment contacting with the heads and casing. Preferably and as heretofore stated, I employ packing rings between the face of the abutment and the casing and heads. While such packing may be of any suitable construction, I have represented in Fig. 21 packing strips 83 preferably formed of short strips 83^a—83^a received within the ends of the recess 82 to engage with the heads. The outer ends of said strips 83^a at the point where they contact with the casing are angularly formed and are engaged by packing strips 83^b—83^b having correspondingly shaped contacting ends to provide a close corner fit between the abutment, the casing and the heads. While any suitable packing means may be provided, preferably I provide a pair of packing strips 83^b as shown, and interposed between them the packing strip 83^c, the ends of which are angular, as represented at 83^d, to engage the correspondingly shaped ends of the strips 83^b. Preferably, and as represented in Fig. 21^a, the intermediate packing strip 83^c is provided at its ends with tongues 83^e to engage grooves 83^f formed upon the adjacent ends of the strips 83^b. I have herein represented the strips 83^c as provided with pins 83^g to engage elongated slots 83^h formed in the ends of the strips 83^b. Preferably, each of the packing strips is normally outwardly pressed by a spring 83ⁱ interposed between it and the abutment. It will be apparent that with the described illustration the strips 83^b and 83^c move radially outward to take up wear, the strip 83^c acting, by means of the described connection with the strips 83^b, to move said latter strips 83^b longitudinally of

the abutment and toward the respective heads, thus maintaining a tight fit at all contacting points with the casing and heads. By reason of the angular or beveled construction of the adjacent ends of the strips 83^b and 83^c, it will be apparent that a tight joint is maintained at all times between said strips, thus preventing leakage at such points. Preferably, each of said packing strips is provided with one or more passages 84^a, whereby the oil may be delivered from the reservoir 103^f through said strips. Preferably, the packing strips 69 represented in Figs. 5 and 16 are formed of two end portions, each of which is substantially right angled to engage with the head and the casing and an intermediate portion bridging the space between said end portions and preferably having inclined or beveled ends, such as represented in Figs. 21 and 21^a, in order to prevent leakage at such points. That is to say, the packing strips 69 may have an interposed section similar to the packing strip 83^c, represented in Fig. 21.

Preferably, I provide means for supplying lubricant to the face or faces of the abutment that contact with the rotor. While that may be done in any desired manner, preferably I provide passages 104^a leading from the reservoir 103^b to a channel 104^b, represented also in Figs. 22 and 23 as formed upon the peripheral surface of the trunnions of the abutment. Leading from each channel 104^b is a passage 104^c whereby oil may be delivered to the passages 96 (see Figs. 16 and 17), whereby oil is delivered to the rear face of the strips or holders 85 and whereby the lubricant may also be supplied to the shoe or shoes 86, if the latter be employed. Viewing Figs. 15 and 23 and the arrows upon said figures representing the direction of the rotation, it will be apparent that oil or other lubricant is supplied only to that strip or holder 85 or abutment face that is in operative engagement with the rotor, and that the channel 104^b communicating with the then non-active abutment strip or holder 85 is out of communication with the passage 104^c, the supply of oil thus being cut off from the non-contacting strip or holder.

Viewing Figs. 5 and 15, it will be observed that the wall 57 of the explosion chamber 53 is cut away to a greater extent than the wall 56. In other words the forward wall in the direction of rotation of the rotor is cut away to a greater extent than the opposed wall. This is done in order to permit, as most clearly represented in Figs. 15 and 31, the lines of force of the motive agent to radiate unobstructedly from the wall 56 and preferably at right angles thereto from the extreme forward limit of the explosion chamber, thereby increasing the

leverage upon the rotor, inasmuch as the lines of force of the motive agent engage the same throughout all portions of the peripheral extent thereof that defines one wall 5 of the explosion chamber. In other words, instead of limiting the application of the lines of force of the motive agent to a portion of the rotor radially removed to a considerable extent from the outer concentric, 10 portions 67 and 68, I permit such lines of force to penetrate to and to act upon that portion of the rotor that is radially farthest removed from the point of rotation. It will be apparent that if an explosion chamber 15 53, such as represented in Fig. 5 be employed, I thereby supplement the volume of the explosion chamber 61 within the casing. By so doing I provide a greater number of degrees circumferentially of the casing for 20 the expansion of the motive agent.

Any suitable ignition means may be provided at any suitable point or points within either the chamber or chambers 53 or the chamber or chambers 61. Herein I have 25 represented (see Fig. 7 and Fig. 5) three sparking plugs 105 located adjacent the outer confines of the chamber 53 and suitably connected in any desired manner with any suitable means for admission. If desired, the sparking plugs or certain of them may be mounted within the heads. It is to be understood, however, that any suitable ignition means internally or externally may be employed, my invention being in no wise 30 restricted to any particular type or manner of means.

Viewing Fig. 5, it will be apparent that I have provided a screw threaded plug 106 in the casing opposite the valve head 47, 40 whereby I may by removing said plug readily obtain access to said valve and valve seat to grind the same without removing other portions of the mechanism. If desired, however, the valve mechanism may be 45 removed instead for repairs or for any other purpose.

My invention may, if desired, be embodied in an engine operative in but one direction. I have represented in Fig. 31, such a type 50 of engine. With the exception of the abutment or abutments this form of engine operable in but one direction may be, if desired, substantially that shown in Fig. 5 and elsewhere representing the two-way or reversible type. The abutment or abutments 55 107 in this type of engine need each have but a single edge 108 adapted to contact with the peripheral face of the rotor. Preferably, each abutment, if a plurality be employed, is provided with a trunnion portion 109 received within a suitably recessed portion of the casing, the ends thereof projecting into and being suitably mounted for oscillation with the heads. If desired, a suitable wearing strip 110 may be interposed

between the trunnion portion 109 and the recessed portion of the casing. It will be apparent that the impact upon each abutment is transmitted to and is taken up by the wearing strip or strips 110.

The concentric portions 65, 66 of the rotor are located at such a radial distance from the center of rotation of the rotor and the contour of each abutment is such that when the explosion occurs or the greatest load of the motive agent is received by the abutment, that portion of the abutment forming the rear wall of the combustion chamber extends in a line in advance of a radial line drawn from the center of rotation of the rotor and extending to that point upon the inner surface of the casing where the recessed portion of the casing, wherein the abutment operates, merges therewith, as represented at 112 in Fig. 15. In other words, the exposed face of the abutment is always in advance of such described radial line and consequently receives with the described result the pressure or impact of the motive agent or agents. In this manner the 90 motive agent acts to force such exposed portion of the abutment into tighter engagement with the peripheral surface of the rotor, rather than to elevate the abutment from the rotor, which would be the case 95 were the opposite construction presented. This construction of parts is true both of the reversible type of engine shown in section in Fig. 5, as well as in the one way or non-reversible engine shown in Fig. 31. 100 It is apparent that this feature of my invention may be embodied in types of engines other than that disclosed and wherein the abutment or abutments are otherwise mounted than as here shown.

I contemplate the provision of means for cushioning the outward radial movement of the abutment or abutments. In Fig. 31, I have illustrated one form of mechanism for accomplishing this result. It will be apparent, however, that I may similarly construct the form of abutment or abutments shown in the reversible type of engine illustrated in Fig. 5, or I may secure the same result in other ways in either type of engine.

Referring more particularly to the construction disclosed in Fig. 31, it will be noted that the leading face of each abutment 107 is recessed as represented at 113, thereby providing a shoulder 114, the adjacent recessed portion of the casing within which such abutment works being correspondingly shaped, so that such shoulder 114 may be received within such recessed portion in the outward radial movement of the abutment. 120 When the abutment 107 rests upon the concentric portions 65 or 66 of the rotor, as represented in Fig. 31, it will be apparent that a chamber or recessed portion is exposed between the adjacent faces 115 and 116 of the 125 130

abutment and casing, respectively, for the reception of the motive agent. Upon the further rotative movement of the rotor, the abutment is forced outwardly by an eccentric portion of the rotor, whereby the motive agent received in said recessed portion or chamber is compressed therein, thus cushioning such outward radial movement of the abutment. It will be apparent that 5 after either of the concentric portions 67 or 68 of the rotor has passed beyond the abutment, the latter begins to move radially inward again and that the expansive action 10 of the motive agent in such chamber or recessed portion assists in such described inward radial movement of the abutment. It will furthermore be apparent that the force 15 of the motive agent exerted upon the shoulder 114, when said shoulder is exposed to the action of such agent upon the inward radial movement of the abutment, tends to hold the abutment in tight engagement with the peripheral surface of the rotor. If desired, I may provide means permitting the 20 escape of more or less of the motive agent received in said chamber or recess during the outward radial movement of the abutment and also permitting the inflow thereinto of more or less of the motive agent during inward radial movement of the abutment. I accomplish this in the matter illustrated in Fig. 31, wherein I provide a passage 117, leading from such chamber or recess and communicating with the explosion 25 chamber. It will be apparent that such passage might be located in the abutment itself, communicating with said chamber or recess and with the explosion chamber. If desired, I may place in such passage, whenever located, a suitable valve, such as indicated at 118 in Fig. 31, whereby the passage 30 of the motive agent in either direction may be regulated. It is apparent that I may regulate the compression of the motive agent 35 within such chamber or recess in any suitable way, as, for example, by scoring or cutting away the shoulder 114 of the adjacent face of the casing, thus establishing communication between the explosion chamber 40 and such recess or chamber.

The outward radial movement of the abutment or abutments in either type of engine herein disclosed or in any other suitable form of the invention may be cushioned 45 otherwise than as described. While this result may be accomplished in different ways, in this specific embodiment of my invention (see Fig. 31) I suitably shape the rear portion of the forward face of the rotor or the 50 adjacent face of the casing to provide a chamber or recess 119 for the admission thercinto of the motive agent, which in this embodiment of my invention enters thereinto after passing through the said abutment 55 upon its way to the exhaust. It is apparent

that any other agent may be employed for this purpose. It is apparent, however, that the motive agent may be admitted into such recess in any suitable manner. Preferably, the casing is provided with a shoulder 120 70 and the abutment with a shoulder 121. Upon the outward radial movement of the abutment the motive agent, however introduced into said recess 119, is compressed therein, thereby cushioning the outward 75 movement of the abutment, and the inward radial movement of the abutment at the proper time is arrested by the expansive action of such compressed motive agent. If desired, I may provide means permitting 80 the escape of more or less of the motive agent from said recess 119 during the described outward radial movement of the abutment and the admission of more or less motive agent thereinto during the inward 85 radial movement. This may be accomplished in any suitable manner. Herein I have represented a passage 122 in the abutment, within which I may, if desired, locate a regulating valve 123. It is apparent 90 that such passage, if employed, may be located either in the abutment or in the casing.

I may introduce the motive agent or agents into the engine from any suitable source at normal temperature. If desired 95 and as herein illustrated, however, I utilize more or less of the heat agents given off by the engine in operation to heat the incoming agent or one or more of them if a mixture thereof be employed, thereby returning such 100 heat units or a portion thereof to the engine. It is apparent that the degree of utilization of such heat units depends upon numerous conditions, such, for example, as the nature of the motive agent or agents, the atmospheric conditions, etc. If the motive agent or agents be heated, I may employ any suitable heating medium, as, for example, the exhaust of the motive agent or agents of whatever nature or the temperature regulating agent, if such be employed. In the type of the invention herein represented I have chosen to illustrate the heating of certain of the motive agents by the exhaust. 110

Referring more particularly to the construction shown in Figs. 4, 5 and 20, the exhaust passages are represented at 124. The motive agent introduced through the pipes 37 is passed into heating relation with the exhaust in any suitable manner and herein 120 by the provision in any suitable manner of a chamber 125 surrounding the exhaust and into which the motive agent is introduced from the pipe 37. After passing through such chamber 125 the motive agent issues 125 into the pipes 38 and 39. If desired, I may employ deflecting partitions or fins 126 in said chamber or chambers 125, which may be of a spiral character of suitable extent or of any other suitable form and serve to 130

thoroughly mix the motive agent and to expose all portions thereof to the heat of the exhaust, while prolonging the period during which the motive agent is subjected to the heating action of the exhaust. Furthermore, said fins serve to convey by radiation the heat received by the exhaust to the motive agent through the pipe 37. I may introduce a compressed agent through the pipe or 5 pipes 37, which may be air or any other suitable agent. Such compressed agent is usually introduced below normal temperature from the compressor and when passing into heating relation with the exhaust, is thereby 10 raised in temperature and expanded. Since such expanded agent is then of greater volume, it will be apparent that a less quantity of compressed agent need be introduced from the compressor, thus securing a saving 15 in the amount of the compressed agent employed. I may employ some supplemental means either interiorly of the engine or exteriorly thereof to heat the compressed agent introduced through the pipe or pipes 37. 20 This may be found desirable in case the engine is operated wholly by the compressed agent introduced through said pipe or pipes 37.

If a second motive agent be introduced 25 into the engine, as, for example, through the pipes 42 and 43, represented in Figs. 5 and 31, or otherwise, I may heat such agent in any desired manner, as by passing the same into heating relation with the exhaust 30 or with the temperature regulating agent, if the latter be employed, thereby returning to the engine more or less of the heat units thrown off in its operation. If it be desired 35 to heat such agent by the exhaust, this may be readily done, as by extending the pipe or pipes 43 through the exhaust passage or passages 124, as represented at 127 in said figures.

I have described a construction wherein, 40 if desired, one or more motive agents may be introduced into the combustion chamber through the rotor and whereby one or more motive agents may be introduced into the combustion chamber through the casing. It 45 will be apparent that any of said motive agents may be heated by the means described or in any other suitable manner. For example, the motive agent introduced through the pipe or pipes 37, after being heated, if desired, may be introduced into the combustion chamber, both through the casing and through the rotor. The motive agent introduced through the pipes 42 and 43 may be heated prior to its admission into 50 the combustion chamber through the casing and if another agent or agents be introduced into the combustion chamber, as through the rotor, such agent or agents may receive a preliminary heating by the exhaust or by 55 the temperature regulating agent in the

manner described or in any other suitable way.

Preferably I introduce a temperature regulating agent or agents of any suitable character into one or more parts of the engine. Such agent may be of any suitable nature, as, for example, water, air, steam, a refrigerating agent, or the like. If desired, I may introduce one agent into one portion of the engine and another agent or agents into other portion or portions thereof, or I may introduce the same temperature regulating agent into such portions of the engine as it is found desirable to subject to the action of temperature regulating means. However such agent or agents be introduced, I may provide means for regulating their passage through the part or parts to which they are applied to meet the needs of the respective parts, inasmuch as under certain conditions certain portions of the engine may need greater amounts of the temperature regulating agent or agents than others. In the present type of the invention, I have chosen to represent the introduction of a suitable temperature regulating agent, as, for example, water, into one portion of the engine and the circulation thereof through such other portions of the engine as should be subjected to the action thereof. Referring to the single embodiment of my invention herein represented, and particularly to Figs. 4, 5, 6, 10 and 46, I introduce (see Fig. 6) a suitable temperature regulating agent from any desired source, as from a reservoir 127, the top of the water column wherein is not lower than and may be substantially the same as the highest level assumed by the temperature regulating agent in the circulation through the engine or otherwise in such manner that the discharge of the heated outgoing agent is so arranged as to provide for a continuous circulation 100 through the engine. The agent then passes through the pipe 128 into the shaft 2 in any suitable manner, as by the provision of a collar 129 having formed between itself and the shaft an annular chamber 130, from which the agent is introduced to the axial line of said shaft, where it is received in the longitudinally disposed chamber or passage 132, thus keeping the shaft cool. Preferably, I next introduce the agent into the rotor, as clearly represented in said figure and also in Fig. 5. In the operation of the engine, the said shaft and rotor act as a centrifugal pump, whereby the agent is forced or thrown under centrifugal action outwardly to the desired extent. Herein the chamber or passage 132 is represented as provided with a transverse passage 133 communicating with the interior of the rotor, which is provided with one or more passages 134 of any desired extent. Herein, and merely for convenience of operation, I have repre-

sented one passage 134 communicating with one end of the transverse passage 133, and a second passage 135 communicating with the opposite end of said transverse passage.

5 It is apparent, however, that the passage 134 may be of any desired extent and may circulate the agent throughout the rotor as desired. Preferably, the passage or passages within the rotor are of relatively reduced extent in cross section, this construction which I preferably employ being distinguished from one wherein a temperature regulating agent is conveyed into a rotor having an enlarged chamber therein.

10 In such last referred to construction, there is not secured a thorough action of all portions of the agent upon the walls of the rotor, nor is the temperature of the rotor rendered even throughout all its parts, as is accomplished by the uniform application of the heating agent to such parts of the rotor through which it is distributed. Preferably the passage or passages within the rotor are so disposed that the temperature 15 regulating agent is conveyed to points near the periphery thereof, as represented in Fig. 5. It will be apparent that in the manner described, the entire body of the temperature regulating agent is constantly circulating through the rotor and does not pocket therein, as would be the case were an enlarged chamber or chambers provided within the rotor for its reception.

The temperature regulating agent introduced into the rotor may be withdrawn therefrom in any suitable manner, as through one or the other or both of the heads of the casing. Preferably, however, I withdraw such agent through the shaft 2, and for that 20 purpose are herein represented (see Fig. 6) one or more passages 136 which, to secure the most effective operation of the centrifugal pumping action referred to, should be disposed at a greater radial distance from the axis of rotation of said shaft than the chamber or passage 132, it being apparent that by this construction the centrifugal force or energy whereby the agent is introduced into the rotor is not neutralized by 25 the centripetal action, whereby said agent is withdrawn therefrom. I may, if desired, employ suitable means to prevent leakage of the temperature regulating agent along the surface of the shaft 2. To that end, I 30 preferably provide (see Figs. 6 and 7) packing rings 136' of any suitable description tightly fitted between said shaft and received within suitably recessed portions of corresponding shape provided in opposite faces of the rotor. It is apparent that any means may be employed to prevent leakage along the shaft. The passage or passages 136 may be continued throughout the shaft 2 as desired. Herein, I have represented them as 35 terminating at a collar 137 mounted upon said shaft at any suitable point, an annular chamber 138 being provided between it and said shaft, from which chamber the agent may be withdrawn and discharged or led to any other part or parts of the engine as desired. Herein, I have represented such agent when discharged from such chamber 138 as introduced (see Fig. 4) into pipes 139 leading in any desired manner to the abutment or abutments 60. Herein, I have 40 represented each abutment as provided with a screw threaded removable plug 140 at one end, which may be provided with an outer frusto-conical surface 141 to serve as a bearing for a collar 142 received thereon and provided with a chamber 143, into which the agent is introduced from the pipe 139. Preferably, a coil spring 144 is located between such collar 142 and the abutment, tending to force outwardly the collar 142, 45 thus maintaining a tight fit between the same and the frusto conical surface of such plug, the latter being provided with a passage 145 adapted to register with the chamber 143 and to introduce the temperature 50 regulating agent into the interior of the abutment. It will be apparent that the temperature regulating agent is so conveyed to the rotor, is so circulated therethrough and is so delivered to the succeeding part or 55 parts that are to be subjected to its action that such agent is not pocketed in whole or in part in any portion of the engine. In this manner, I secure a uniform action of all portions of the agent in each part that 60 is subjected to its action so far as possible. Each abutment is provided with a suitable passage 146 preferably of restricted area in cross section, in order to prevent pocketing of the agent therein. If desired, such passage 65 may surround the exhaust opening 80 in the abutment, if the latter be provided. The motive agent, having circulated through the abutment or abutments in the manner described, is withdrawn therefrom in any suitable manner, as through plugs 147 at the opposite ends of the abutments, similar in construction to the plugs 140, and is thence conveyed by means of a collar 148 into a 70 pipe 149, by which it may be discharged 75 from the engine. Herein, however, I have represented the agent as conveyed (see Fig. 10) by means of the pipe or pipes 149, preferably into the upper portion of the forward head 5 (see Fig. 4), which for that purpose 80 is provided with suitable passages 150 preferably of reduced area in cross section to prevent pocketing of the agent therein. Viewing Fig. 10, it will be observed that I 85 preferably withdraw the temperature regulating agent from the heads at the lower portion thereof, as represented at 151. It may then be discharged from the engine, but herein I convey it by means of a pipe or 90 pipes 152 to the casing, and preferably at the 95

upper portion thereof as represented at 153 (see Fig. 7 and 10).

It will be observed that in the distribution of the temperature regulating agent, I aim so to introduce the same that a thorough mixing of the portions of each agent is secured in each part to which it is introduced. Viewing Figs. 5 and 7, it will be apparent that the agent is introduced into the casing into channels or recesses 154, by which it is preferably distributed throughout all necessary portions of the casing. It will be apparent from said figures that the agent is circulated preferably first about that portion of the casing through which the motive agent or agents are introduced into the upper mixing chambers 46-46. Thereafter, the agent may be conveyed to and circulated through all desired portions of the casing. For example, viewing Fig. 5, it will be observed that after the agent has been circulated about such mixing chambers and the parts coöperating directly therewith, it is introduced into that portion of the casing forming the outer wall of the explosion chamber or chambers. In this manner, I may, if desired, completely surround the entire casing, excepting where the same is provided with necessary passages, wherein the temperature regulating agent is circulated. Preferably, the temperature regulating agent is thus conveyed in a narrow sheet to a point closely adjacent the inner surface of such casing and also to points near the heads. It will be observed that such channel 154 passes about the exhausts 124 and also about the lower combustion chambers 53 as well as the mixing chambers leading thereto and the parts directly associated therewith. The temperature regulating agent, having circulated as described or in any other suitable manner through the casing, is withdrawn therefrom as desired and preferably at or near the bottom thereof, as represented at 155-155 in Fig. 10, it then being, if desired, discharged from the engine; but preferably it is led into the other or rear head 6 at or near the top thereof and is circulated therein through a channel 156 (Figs. 4 and 7) in a manner already described with reference to the head 5. After circulating through the second head, the agent is withdrawn therefrom and preferably at the bottom (see Figs. 5 and 10) by means of pipes 157, when it may be discharged into any suitable receptacle to be cooled if desired and again circulated through the engine. It is apparent that the temperature regulating agent, not only in its passage from one part of the engine to another, but when finally discharged therefrom, may be utilized to heat one or more of the motive agents, thereby performing a two fold function and returning to the engine more or less of the heat units taken therefrom.

One or more of the incoming agents may be suitably screened prior to its introduction into the explosion chamber. This may be done in any suitable manner, as by the introduction of a fine wire gauze 157 (see Fig. 45) in the pipes or passages whereby the motive agent or agents are introduced into the chamber. In this manner, the motive agent or agents are introduced into the chamber free of any foreign substance. 75

I may, if desired, employ suitable packing to be interposed between one or both of the heads where inset into the casing, so as tightly to pack the portions of the casing and heads contacting at such points. Viewing Figs. 4 and 7, it will be observed that I have represented at 158 packing strips which may be and preferably are similar in construction to the strips 75 and 76 provided upon the abutments. If such strip or strips 158 should not entirely encircle the head or heads, set screws or other means may be provided to retain in position such segmental strip or strips. 80

I may, if desired, introduce a temperature regulating agent into one or both of the tapering bearings 3. While such agent may be introduced from the general system of distribution of a temperature regulating agent hereinbefore described, preferably I introduce a separate agent. Viewing Figs. 11 to 14, it will be observed that I have provided each bearing with annular chambers 159 and 160 and communicating in any suitable manner, as by passage 161. Any suitable agent and preferably a cold lubricant, such as oil, is introduced into the chamber 159 from the exterior, and after circulating therethrough is discharged into the chamber 160 from which it works through the action of centrifugal force along the inner face of such bearing 3 and between the same and the adjacent face of the rotor along which it is distributed. 100

The valve or valves 47, whereby the motive agent or agents are introduced into the combustion chamber, may be so arranged as to be opened by the pressure of such agent or agents, thus operating in a manner similar to the check valves 45. Preferably, however, I provide means whereby said valves are mechanically and intermittently opened during the operation of the engine. Any suitable means may be employed for this purpose. As representing merely a type of means that may be employed to this end, I mount (see Fig. 6) a gear 162 fast upon the shaft 2 with which meshes one or more idler pinions 163, herein corresponding in number to the number of valves to be operated, said pinions being mounted in any suitable manner upon the engine. If a plurality of valves be employed, as here represented, each of said pinions 163 gears with a pinion 164 (see Figs. 2, 3, 6, 8 and 9) keyed upon a 120

shaft 165 mounted in suitable bearings 166—166 upon the frame of the engine, the said shaft being provided with a key way 167 permitting axial movement of said shaft relatively to the gear 164. If desired, a bushing 168 rotatable with said shaft may be interposed between the same and that bearing 166 adjacent the pinion 164. Any suitable means may be employed to operate 10 the valves 47 from said shafts 165. Preferably, however, I mount upon each shaft 165 a sleeve 169 carrying thereon oppositely disposed cam projections 170, (see also Figs. 26 and 27) whereby during the rotation of 15 such shaft the valve 47 may be suitably operated. If desired, means may be employed intermediate the valve 47 and the cam projections 170. Herein (see Figs. 5 and 6), I mount a short stud 171 in the framing, 20 whereon are loosely mounted one or more lever arms 172, the number of which depends upon the number of valves that it is desirable to operate from a single shaft 165. Each lever arm 172 may, if desired, be provided with a roll 173 bearing upon the sleeve 169. Each lever arm 172 is adapted to engage the spindle 174 of the respective valves 47, it being apparent that if desired the valve spindle might directly engage the 25 sleeve 169, thus dispensing with said lever arms and parts directly connected therewith. Preferably, I employ one or more coil springs 175 (see Fig. 6) to maintain said rolls 173 in engagement with said sleeve 169. 30 If desired, a suitable spring 176 (see Fig. 5) may be employed tending to close the valve 47 and to maintain the spindle thereof in engagement with the lever arm 172. The valve spindle 174 may be mounted in a suitable 35 valve casing 177 that may be screw threaded as represented into the main casing of the engine. I may, if desired, interpose a spring 178, herein represented as a coiled spring, upon the piston or valve stem disk 47" and positioned between the piston 178' 40 loose upon the valve stem and engaging an annular lip 178" upon said stem and some suitable abutment, as, for example, check or other nuts 179 mounted upon the valve 45 spindle, such spring therefore tending normally to force such piston 47" into engagement with the seat provided therefor upon the valve stem disk 47", thus maintaining a 50 tight fit of such part, yet affording a yielding means in the event of back firing or explosion within the mixing chamber 46, as has been previously described. It is apparent moreover that by the provision of the nuts 179, the tension of the spring 178 may be 55 varied to regulate the pressure at which the valve will open in the operation of the engine or automatically by the pressure of the motive agent.

In the event of an explosion occurring in 60 the chamber 46 between the valves 45 and 47,

the result is to close the check valve and to compress the piston 47" upon the piston stem against the tension of the spring 47", until such piston is received by the shoulder 47'" of the valve casing, whereupon the 70 gases act to open the valve 47, permitting the escape thereof past the same into the combustion chamber.

In that type of my invention that is embodied in a reversible or two way engine, 75 preferably I operate from a single shaft 165 (Figs. 5 and 6) two valves 47, one to be operated when the engine is operative in one direction and the other to be operated when it is operative in the opposite direction. 80 This I preferably do for compactness of construction. In employing such construction, I preferably provide two cams 170 upon said shaft 165, one of them to engage respectively the rolls 173 upon the lever arms 172. I 85 may desire to vary both the amount of lift or openings of said valve or valves 47 and also to regulate the time of lift or admission of the motive agent or agents past said valve and the time of cut off. This may be 90 variously accomplished. Preferably I mount said shaft 165 for axial movement, and taper each cam 170 both circumferentially and radially, as represented in Figs. 26 and 27. That is to say, each of said cams gradually 95 increases in height or radial extent as well as in extent circumferentially of the shaft, it being apparent that when the lower portion of the cam is in operative relation to the valve, such valve is lifted to a less extent 100 and is lifted at a later period and closed at an earlier period than when the higher portion of the cam is in operative relation to the valve. This construction is of advantage, since the higher the speed, the earlier 105 the valve is opened in order to permit scavenging through the combustion chamber, and the earlier the filling of the combustion chamber is begun. In the reversible type of engine, it is apparent that when one 110 of the cams 170 is in operative relation to its valve the other cam is axially removed from axial relation with its valve. In the one way type of engine wherein my invention may be embodied the axial movement of 115 the shaft 165 is effected merely to change the time and extent of lift of the valve.

In that type of my invention embodied in a reversible engine I employ suitable means for reversing certain of the parts. While 120 any means may be employed to this end, preferably and as herein illustrated, I provide a single means controlling the operation of each of the parts, which is herein represented as adapted to be manually operated. Referring more particularly to Figs. 1, 4 and 6, I provide an operating lever 180, herein having an annular sleeve like portion mounted for circumferential movement upon a sleeve 181 spaced somewhat from the shaft 125 180

2, said sleeve being supported at one end by brackets 182 extending from the head 5. Preferably, at the opposite end of the shaft 2, I provide a sleeve 183 similarly spaced therefrom and (see Figs. 4 and 6) similarly supported by brackets 184 from the head 6, such duplication of sleeves being provided to permit corresponding movement of the parts at opposite ends of the casing. The 10 lever 180 is provided with a sleeve 185 (see Figs. 6 and 8) having a projecting lug 186, to which is pivotally connected (see Figs. 2 and 8) a link 187 permitting universal movement. To said link is pivotally connected a link or rod 188, to which is pivotally connected (see Fig. 1) one arm 189 of a bell crank lever mounted upon the frame at 190, the other arm 191 thereof being pivotally connected to a link 192 connected to 20 a bell crank lever 193, to which is connected a universal link 194 having pivoted thereto a member or link 195, which in turn is connected by a universal link 196 to a lever sleeve 197 corresponding in function and 25 preferably in construction to the lever sleeve 185 at the opposite end of the casing. It is apparent that I may provide a lever handle or other operating means 180 at either or both ends of the engine. Each sleeve 181 30 and 183 is supported as described at one end and is also additionally supported by means of a split bearing, the upper member 198 whereof (see Fig. 8) is supported by webs 199 from each head and is provided 35 also with the lower half bearing 200 for a reversing shaft to be described. A lower half bearing 201 is secured by bolts 202 to the half bearing 198, said upper and lower half bearings encircling the respective 40 sleeves.

While any suitable means may be employed to move the abutment or abutments and rotor radially with relation to each other during their relative radial movement 45 in the operation of the engine, preferably I provide means positively to hold the active face of the abutments in engagement with the peripheral face of the rotor, such holding means being preferably such as to permit sufficient yielding to accommodate unevenness in the parts or to take up wear, and I further contemplate, if desired, the adjustment of such yielding means. While any described mechanism may be used to this end, 50 preferably I mount (see Figs. 4 and 6) cams 203 at opposite ends of the casing and upon sleeves 204 rotatably carried by the shaft 2. While a plurality of cams is employed for evenness of operation, it is apparent that a 55 single cam or other means may be employed. Each cam, if a plurality be employed, is provided with a cam groove 205 for the reception therein of a cam roll 206, shown also in Figs. 8 and 9. In order to transmit motion 60 from the cam roll to the abutment, herein I

have represented (Figs. 4, 8 and 9) a guiding segment 207 having therein a segmental slot 208 carried at each end of the abutment, being herein for convenience connected thereto by a pair of webs 209 (see Fig. 4). 70 Mounted upon sleeves 210 (see Fig. 4) upon either sleeve 181 are preferably a plurality of herein diametrically opposed radial guides 211 (see Fig. 8), each having a radial slot 212, through which passes for radial 75 movement therein the pintle 213 of the cam roll 206 and a sliding block 214, to either or both of which is pivotally connected a link 215 pivotally connected by a bolt 216, near one end of a segmental link 217 having there- 80 in a segmental slot 218. Preferably I provide means whereby the movement of the cam roll imparted thereto by the groove of the cam is yieldingly transmitted to the link 217, and thence to the abutment. Viewing 85 Figs. 8 and 9, it will be apparent that by the described operation, the cam acts upon the leading or operative portion of the abutment to draw it into or hold it in engagement with the rotor, this being contradistin- 90 guished in the preferred embodiment of my invention from a construction wherein the connection from the cam or other operating means is to the non-bearing portion of the abutment; that is to say, viewing Fig. 5, the 95 cam operates to draw inward the upper or operative edge of the left hand abutment rather than to push outwardly the lower or non-active edge of the abutment, thus avoiding the friction and cramping that would 100 result between the abutment and recess wherein the same is mounted, as will be clearly apparent. Moreover the radial inward drawing or holding action of the cam acts through a true radius, and therefore 105 most directly and effectively upon the abutment. While any suitable means may be employed for that purpose, herein (see Figs. 4, 110 8, 9, 24 and 25), I form the link 215 in two parts shown more particularly in Fig. 24, wherein the member directly connected to the pintle of the cam roll is radially slotted to receive between it and the other member of the link working therein a coil spring 219 115 so arranged that the movement of the cam roll acts first to compress the spring and thereafter to move inwardly the active face of the abutment. Preferably, I provide means 220 of any suitable description to adjust the tension of such spring. In this manner, not only is each abutment positively held in engagement with the rotor, but it is held with an adjustable yielding pressure.

Mounted in the segmental slot 218 of the link 217 is a slide block 221, through which 125 passes a bolt 222, upon which are also loosely mounted suitable sliding blocks received in the guiding segment 207 and in the radial guide 211. The segmental link 217 is pivoted for rocking movement upon a bolt 223 130

carried near the outer end of a radial arm 224 (see Figs. 4, 8 and 9) which is mounted upon a sleeve 225 (see Fig. 4) carried by the sleeve 181.

5 Whether my invention be embodied in a one way or a reversible engine, I may and preferably do employ suitable means yieldingly and yet positively to hold the abutment or abutments in engagement with the peripheral face of the rotor. If my invention be embodied in a reversible engine, I employ means permitting suitable operation of the abutment or abutments. Assuming the rotor of a reversible engine to be rotating in the direction of the arrow in Fig. 8, it will be apparent that the relative position of the radial guide 211 and the arm 224 for the pivotal movement of the link 217 remains unchanged during the operation of 10 the engine in such direction. During such period, it will be apparent that the active heads of the abutments 60 are held in engagement with the peripheral surface of the rotor, as represented in Fig. 5. During the 15 rotation of such rotor in the described direction, the active face of the abutment is moved radially outward and inward by means of the cam or cams 203, the contour of which substantially corresponds to that 20 of the rotor. Thus, the position of the active face of each abutment is changed radially in exact accord with the contour of the rotor, so that as a concentric portion 65 or 66 of the rotor is presented to the abutment the 25 active face of the latter is held in its inner radial position, and as an eccentric portion of the rotor succeeds a concentric portion the abutment is held in a position of greater radial distance, this operation continuing 30 throughout the rotation of the rotor in one direction. When it is desired to reverse the engine, and herein by reversing the direction of rotation of the rotor, I prefer to move the abutment or abutments into neutral 35 position out of engagement with the rotor. Viewing the position of parts illustrated in Fig. 8, it will be apparent that the leverage for rocking movement imparted to the abutment in accordance with the rotation 40 of the rotor is the distance between the center of the bolt 223 and the center of the bolt 222. In moving the abutment or abutments into neutral position, I impart a slight circumferential movement to the sleeve 225 whereon arm 224 is carried, in the direction 45 of the arrow represented in Figs. 8 and 9, carrying the center of the bolt 223 into the same radial line with the center of the bolt 222, which bolt 222, if not removed equidistant from the axis of the rotor by the movement of the cam is moved by the segmental link to be directly beneath the center of said bolt 223. Such movement of the arm 224 carries with it the link 217, which is then 50 extended beyond the radial guide 211, into 55 the position shown in Fig. 9. When the abutment is in neutral position, each face thereof is housed within the recessed portion of the casing provided therefor. In such position of the parts, the rotor in its movement, still in the forward direction, does not contact with the abutment, and the admission valves to the engine being closed, the rotor merely operates idly. Prior to the commencement of rotation of the rotor in 60 the opposite direction, I move the abutment from neutral position to a position wherein the previously inactive edge is now presented for engagement with the peripheral surface of the rotor. This is accomplished in this type of the invention by moving the radial guide 211 and the radial arm 224 in unison in the direction opposed to the direction of the arrow shown in Fig. 8, until said two parts arrive at the lower end of the slot 65 208 in the guide 207, viewing said Fig. 8. Thereafter, the movement of the radial arm 224 in the same direction is continued, thus circumferentially removing again the bolt 223 from the bolt 222 to provide leverage for 70 the rocking movement of the abutment when the engine operates in the reverse direction. In order, in reversing the abutment, to bring the previously inactive face properly 75 into engagement with the rotor, I preferably circumferentially impart a slight movement of rotation to each cam 203 with respect to the rotor, thereby to maintain the same relation of the cam and the rotor when 80 operating in the reverse direction that they 85 previously had when operating before reversing.

Preferably I provide means for imparting more or heavier inward pressure or pull upon the abutment than is imparted in the outward movement of the abutment, in order to hold the abutment in tighter engagement with the rotor when the pressure is on, as by explosion or otherwise depending upon the motive agent used. This may be accomplished in any suitable manner. Herein, however, I accomplish this by imparting a suitable formation to the cam or cams 203 and also if desired, by imparting a slight movement of relative rotation to the cam 110 and rotor, as by moving the cam with respect to the rotor at the period of reversal. In the one way type of engine, this function would be accomplished by suitably shaping the cam to that end. I find it desirable in 115 certain types of engines, and particularly in reversible types, to have the rotor slightly lead the cam for operating the abutments, owing to the unequal radii of said parts and the leverage of the co-acting members. If 120 I do employ such feature of construction, then in reversing the engine, I impart such relative movement to the rotor and cam as to maintain this relation. It will be understood, however, that the position and shape 125 130

of the cam or cams 203 is such as to impart movement to the abutment or abutments exactly commensurate with the contour of the rotor.

5 When the previously inactive face of the abutment is moved into engagement with the rotor preparatory to reversal of the engine, the rotor is still turning in the forward direction or in the direction of the arrows 10 in Figs. 5 and 8. The result of this action is that the abutment is so presented that the rotor compresses between it and the casing and such abutment whatever fluid may be within the casing, thus providing a buffer 15 opposing the continued rotation of the rotor in such direction, and thereby checking its movement. This buffer action may continue until the rotor is brought to a state of rest. During the described action, the engine acts 20 as a compressor. The timing of the parts, however, is preferably such that before full compression of such remaining fluid the valve or valves operative upon the reverse rotation are opened, thereby admitting a 25 charge into the explosion chamber, unless the action of compression be so great as to force the incoming motive agent or agents backward; in which case, owing to the described action of the engine as a compressor, 30 upon a subsequent rotation, the proper admission of the motive agent is effected. It will be apparent that the engine, acting as a compressor, may suck in through the exhaust, filling the chamber and compressing 35 the fluids against the valves, which in turn will be opened at the proper time depending upon the timing of the parts. It will be understood, viewing Fig. 5, that when the engine is operating in a forward direction 40 or in the direction of the arrow, the active valves are those indicated as A and B and that when the engine is operating in the opposite direction the active valves are those indicated as C and D. Correspondingly, 45 viewing Fig. 15, when the engine is operating in a forward direction, the operative ports admitting motive agents into the rotor are the ports a and b, the fluid being admitted through the ports c and d in the reverse operation of the engine.

50 Any suitable means may be employed to operate the mechanism for moving the abutment or abutments into neutral position or for shifting them for the reversal of the engine, it being understood that in certain types of reversible engines embodying my invention it is unnecessary to move the abutment or abutments into neutral position when reversing. Also, any suitable means 55 may be employed to operate the valve or valves for introducing a motive agent or agents into and through the rotor and into the combustion chamber through the casing. Preferably, however, I provide means 60 whereby these various operations may be

performed from a single device or mechanism.

Referring first to the mechanism for manipulating the abutment or abutments, and referring to Figs. 4, 8 and 9, I herein preferably provide the sleeve 210 (see Fig. 4), whereon each radial guide 211 is mounted with a segmental gear 226 meshing with a pinion 227 loose upon a short shaft or stud 228 carried in a suitable bearing 229. Fast 70 upon said shaft 228 is a worm gear 230 (see also Figs. 28 and 29). Carried by the pinion 227, as by the hub thereof, are ears or brackets 231 and 232, wherein is mounted a worm 233 meshing with the worm gear 230, 80 it being apparent that movement of the segmental gear 226 is transmitted through the pinion 227 and worm 233 to the worm gear 230. Upon the shaft of the worm 233 is a handle 234, upon manipulation of which the 85 relative position of the pinion 227 and the worm gear 230 may be altered. Fast upon the shaft 228, and herein upon the other side of the bearing 229 (see Fig. 9), is mounted a segmental gear 235 meshing with a pinion 90 236, upon the axle 237 whereof (see Fig. 6) is carried or formed the small gear wheel 34 for operating the valve or valves whereby the motive agent or agents are admitted into the rotor. It will be apparent that any 95 means may be employed for operating such valves, the described mechanism being merely one form of means whereby the result may be accomplished. It is apparent that by the described manual manipulation 100 of the worm 233, the circumferential position of the valve or valves admitting the motive agent or agents into the rotor may be regulated, thus regulating or varying the time of admission with relation to the rotation of the rotor.

While any suitable means may be employed circumferentially to shift the abutment operating cam with relation to the rotor, if this action be performed, herein I have 110 represented (see Figs. 6, 8 and 9) a lug 238 upon the sleeve 210, whereon the radial guide 211 is mounted. Pivotally connected to such projection is a universal link 239 having connected thereto one member 240 115 (see Figs. 1, 4 and 6) of a bell crank lever mounted upon a stud 241, the opposite member 242 of said lever being forked and provided with lugs or rolls 243 engaging the annular groove of a spool 244 splined upon the shaft 2. As more clearly represented in Fig. 36, each spool has extending from the inner face thereof and within the sleeves 120 181 or 183, as the case may be, preferably a key or keys or encircling sleeve or the like 125 245 extending axially of the shaft and resting upon the periphery thereof. Near the opposite end of said key or keys or sleeve, each key, if this construction be employed, is provided with a shoulder or lug 246, 130

which is inclined in a direction circumferentially of the shaft, as shown most clearly in plan in Fig. 36. Each of said shoulders or lugs enters a similarly inclined groove or recess 247 formed in the cam 203 (see Fig. 4) that operates in unison with the rotor and governs the action of the abutment or abutments. Herein, each key 245 is represented at 248 as extended axially of the shaft 2 beyond the shoulder or lug 246 to steady the operation of said key or keys. It will be apparent that when a movement is imparted to the spool 244 axially of the shaft 2, a slight movement of partial rotation is imparted to the cam 203 in a direction depending upon the direction of movement of said spool.

Any suitable means may be employed axially to move the shaft or shafts 165 (see Fig. 6), thereby to control the operation of the admission valve or valves. As representing one form of means for accomplishing this result, I have shown (see Fig. 6) the sleeve 210 at the rear end of the machine 25 and carrying a radial arm, as provided with a lug 249 having mounted therein a pin 250 upon which is pivotally mounted a sleeve 251, shown also in Fig. 1. To said sleeve is pivotally mounted at 252 (see Fig. 1) a rod 253 operatively connected to one arm 254 of a bell crank lever pivoted at 255, the opposite arm 256 thereof being connected, as by a pin and slot connection 257, to the shaft 165. It will be apparent that, when 35 a movement of partial rotation is imparted to the sleeve 210, an axial movement is imparted to the shaft 165. I may connect the rod 253 and lever arm 254 in any suitable manner to permit the proper rotation 40 of the parts. Herein, for the purpose, I have represented, as shown more in detail in Fig. 30, the rod 253 as having mounted thereon for axial movement with respect thereto a sleeve 258 having an annular 45 groove 259 receiving therein segmental members 260 receiving therein pins 261 screw threaded into a ring 262 having oppositely disposed trunnions 263 received within suitable bearings upon the lever 254. It will 50 be apparent that by the described connection movement is permitted of the parts in two different planes; that is to say, a rotative movement upon the trunnions 263 and a movement circumferentially of the 55 rod 253.

It has been heretofore stated that in this type of the invention, I have employed a single operating means, namely, a sleeve 185 at the front end of the engine and provided 60 with a handle 180 to control the entire reversing operation. In order to impart the previously described movements to the radial arm 224 and the radial guide 211 (see Fig. 8) from said sleeve 185 and handle 180, I employ any suitable mechanism. Prefer-

ably, as shown in section in Fig. 6 and in detail in Figs. 37 to 44, I provide the sleeve 185 with a first series of segmental teeth 267, the first series being adapted to mesh with the teeth of a mutilated gear 269 fast upon a short shaft 270 suitably mounted in the framing of the engine. Loosely mounted upon said shaft is a sleeve 271 having keyed thereon a mutilated gear 272, which is adapted to mesh with the second series of 75 segmental teeth 268. Carried by the handle 180 is a segmental portion 273 having thereon a single tooth 274 adapted to mesh at certain times with the mutilated gear 272, said segmental portion extending across the 80 gear 269 but having no operative engagement therewith. Near its opposite end the shaft 270 is provided with a pinion 274 adapted to mesh with the teeth upon the sleeve 210 carrying one of the radial guides 85 211. Fast upon the sleeve 271 at its opposite end is a pinion 275 meshing with the teeth upon the sleeve 225, whereon is mounted the radial arm 224. By the described 90 connections, representing merely one form 95 of means for suitably operating the parts, the abutment or abutments are moved first into neutral position and then into the reverse position in the following manner. Referring to Fig. 8, during the operation of the engine in a forward direction, the position of the radial guide 211 and the radial 100 arm 224 is that there indicated. During such position of said radial guide and radial arm, the segmental gears 267 and 268 are 105 out of mesh with the mutilated pinions 269 and 272 respectively, the single tooth 274 upon the segmental portion 273 being in engagement with the tooth 276 of the mutilated pinion 272. In moving the radial arm 110 224 into substantial coincidence with the radial guide 211, the movement of the handle 180 and of the sleeve 185 imparts a movement of partial rotation to the mutilated gear 272, bringing it into the position shown 115 in Fig. 40, at which time the tooth 274 has moved from engagement with the tooth 276 upon such pinion. Such movement has brought the segmental teeth 268 into position to engage the teeth of such mutilated 120 gear, as represented in said figure. During such movement of the handle, no movement has been imparted to the radial guide 211, but, as represented in Fig. 39, the segmental teeth 267 have been moved into position to 125 mesh with the teeth of the mutilated gear 269. In this position of the parts, the abutment, or the abutments if a plurality be employed, has been moved into the previously 130 described neutral position. Upon the continued movement of the handle 180 in the same direction, I move the radial guide 211 and the radial arm 224 in the direction opposite to the arrow in Fig. 8 and in unison as has been described. When this move-

ment is accomplished, the abutment is still in a neutral position. This reverse movement of the radial guide 211 and radial arm 224 is accomplished as illustrated in Figs. 42 and 41, wherein it will be apparent that the segmental teeth 268 being brought into engagement with the mutilated pinion 272 rotates the same in the direction opposite to which it was previously rotated by the teeth 274, thereby reversing the movement of the radial arm 224. At the same time, the segmental teeth 267, as represented in Fig. 41, have engaged the teeth of the mutilated pinion 269, rotating the same in the direction of the arrow thereon, thus moving the radial guide 211 in the same direction. In order to move the abutment in the reverse position, it is now merely necessary to continue the movement of the radial arm 224 past the position assumed by the radial guide 211. This movement is represented in Fig. 44, wherein it will be observed that the segmental teeth 268 have imparted a further movement of reverse rotation to the mutilated gear 272. During this movement, no further movement has been imparted to the mutilated pinion 269 by the segmental gear teeth 267. The abutment or abutments have thus been brought into the reversed position. When it is desired to operate the engine again in the forward direction, the described operation is merely reversed. It will be apparent that, in order to reverse the engine, movement is imparted to the handle 180 in one direction only, the single continued movement thereof effecting the entire reversing action.

Referring to Fig. 5, it will be understood that suitable valves are employed for controlling the admission of motive agents through the pipes 37 and 42. I contemplate so operatively connecting such valves that they may be operated in unison, a movement of one valve similarly operating the other valve or valves. If desired, however, I may so operatively connect them that either may be operated irrespective of the other.

Having thus described one type or embodiment of my invention, I desire it to be understood that although specific terms are employed, they are used in a generic and descriptive sense, and not for purposes of limitation, the scope of the invention being set forth in the following claims.

55 Claims:

1. A rotary engine comprising a casing, a shaft having a rotor thereon and positioned within said casing for relative rotation with respect thereto, a head or heads secured to said casing, a tapering portion or portions surrounding said shaft and extending into said rotor, said portion or portions being threaded for axial adjustment with respect to the shaft.

65 2. A rotary engine comprising a casing

and a relatively rotatable rotor mounted therein, heads for said casing, a one-piece abutment mounted for coöperation with the rotor and the casing, the abutment being provided with a stationary, removable, one-piece, wear holder and a movable two point contact shoe directly carried by said holder. 70

3. A rotary engine comprising a casing and a relatively rotatable rotor mounted therein, one or more heads removable from said casing, means removably to secure said head or heads to said casing, said means being adjustable to permit the taking up of wear, and limiting means to determine the extent of movement of said head or heads 80 toward said casing.

4. A rotary engine comprising a casing and a relatively rotatable rotor mounted therein, one or more heads removable from said casing, means removably to secure said head or heads to said casing, said means being adjustable to permit the taking up of wear, and screws to determine the extent of movement of said head or heads toward said casing. 85

5. A rotary engine comprising a casing and a relatively rotatable rotor mounted therein, one or more heads removable from said casing, means for taking up wear between said head or heads and the casing and 90 rotor respectively, and limiting and holding means to determine the extent of movement of said head or heads toward said casing.

6. A rotary engine comprising a casing 100 and a relatively rotatable rotor mounted therein, heads for said casing, one or both of said heads having a portion adapted to engage the inner surface of said casing and having an encircling rim and a tapering 105 portion engaging the rotor, and means for securing said rim or rims to said casing, said securing means permitting the taking up of wear between said head or heads and said rotor. 110

7. A rotary engine comprising a casing and a relatively rotatable rotor mounted therein, heads for said casing, one or both of said heads having a portion adapted to engage the inner surface of said casing and having an encircling rim, means for securing said rim or rims to said casing, said securing means permitting the taking up of wear between said head or heads and said rotor, and limiting means to determine the extent 115 of movement of said rim or rims toward said casing.

8. A rotary engine comprising a casing, a shaft having a rotor thereon provided with end tapering recesses and mounted for relative rotation with respect to said casing, and heads for said casing, said heads having a tapering portion surrounding said recesses of said shaft and extending into said rotor to take up wear or to maintain a tight fit, 120 125

and means to admit motive fluid through both of said tapering portions.

9. A rotary engine comprising a casing, a shaft having a rotor thereon and mounted for relative rotation with respect to said casing, and heads for said casing, some of said parts, namely, said heads and said rotor, having a tapering portion extending into a correspondingly recessed portion of the other to take up wear or to maintain a tight fit, and means to admit motive fluid through both of said tapering portions.

10. A rotary engine comprising a casing, a shaft having a rotor thereon and mounted for relative rotation with respect to said casing, and heads for said casing, said heads having a tapering portion thereon surrounding said shaft, the end face or faces of said rotor being correspondingly recessed to receive said tapering portions to take up wear or to maintain a tight fit, and means to admit motive fluid through both of said tapering portions.

11. A rotary engine comprising a casing, a shaft having a rotor thereon and mounted for relative rotation with respect to said casing, one or more abutments within said casing and contacting with the rotor and having bodily movement toward and from the rotor, heads for said casing, both of said heads having a frusto-conical portion thereon surrounding the shaft and extending into the rotor, whereby the rotor may be centered with respect to said abutments.

12. A rotary engine comprising a casing, a shaft having a rotor thereon and mounted for relative rotation with respect to said casing, a head or heads for said casing, said heads having a tapering portion thereon surrounding said shaft, the end faces of said rotor being correspondingly recessed to receive said tapering portions, said tapering portions having ports to admit motive fluid into the casing, and means to move said tapering portion or portions axially of said shaft.

13. A rotary engine comprising a casing, a shaft having a rotor thereon and mounted for relative rotation with respect to said casing, and a head or heads for said casing, one or both of said heads having a conical portion thereon surrounding said shaft and extending into said rotor to take up wear or to maintain a tight fit, said conical portions each having a port to admit motive fluid into the casing.

14. A rotary engine comprising a casing, a shaft having a rotor thereon and mounted for relative rotation with respect to said casing, and heads for said casing, each of said heads having a frusto conical portion thereon surrounding said shaft and extending into said rotor to take up wear or to maintain a tight fit and to center the rotor with respect to the casing, and means to in-

duce a motive agent through at least one of said heads.

15. A rotary engine comprising a casing, a shaft having a rotor thereon and positioned within said casing for relative rotation with respect thereto, heads secured to said casing, a tapering portion or portions surrounding said shaft, separate from said heads and extending into the said rotor, and means for removably securing said tapering portion or portions to the respective head or heads.

16. A rotary engine comprising a casing, a shaft having a rotor thereon positioned within said casing for relative rotation with respect thereto, heads secured to said casing, a tapering portion or portions surrounding said shaft, separate from said heads and extending into said rotor, and means for moving said tapering portion or portions axially of said shaft.

17. A rotary engine comprising a casing, a shaft having a rotor thereon and positioned within said casing for relative rotation with respect thereto, and heads secured to said casing, there being a bearing portion interposed between said shaft and one or both of said heads and separate therefrom, one of said portions, namely,—said bearing or bearings and said rotor,—having a tapering part extending into a correspondingly recessed part of the other.

18. A rotary engine comprising a casing, a shaft having a rotor thereon and positioned within said casing for relative rotation with respect thereto, heads secured to said casing, a tapering portion or portions surrounding said shaft and separate from said heads, the end face or faces of said rotor being correspondingly tapered to receive said tapering portion or portions, and means for moving said tapering portion or portions axially of the shaft to take up wear between them and said rotor.

19. A rotary engine comprising a casing, a shaft having a rotor thereon and positioned within said casing for relative rotation with respect thereto, heads secured to said casing, one or both of said heads having associated therewith a tapering portion surrounding said shaft and extending into said rotor, and provisions for introducing a motive agent through said tapering portion or portions.

20. A rotary engine comprising a casing, a shaft having a rotor thereon and positioned within said casing for relative rotation with respect thereto, heads secured to said casing, one or both of said heads having associated therewith a tapering portion surrounding said shaft and extending into said rotor, provisions for introducing a motive agent through said tapering portion or portions, and means to move said tapering portion or portions axially of said shaft.

21. A rotary engine comprising a casing, a shaft having a rotor thereon and positioned within said casing for relative rotation with respect thereto, heads for said casing, one or both of said heads having associated therewith a tapering portion extending in said rotor, and provisions for introducing a motive agent or agents through said tapering portion or portions into said rotor to be discharged therefrom into said casing. 70
22. A rotary engine comprising a casing, a shaft having a rotor thereon positioned within said casing for relative rotation with respect thereto, heads for said casing, one or both of said heads having associated therewith a tapering portion extending into said rotor, said rotor and said tapering portion or portions each having a passage or passages therein for the reception of a motive agent or agents, said passages being adapted to register during the relative rotation of said casing and rotor, and means for maintaining a tight fit between the registering mouths of said passages. 75
23. A rotary engine comprising a casing, a shaft having a rotor thereon and positioned within said casing for relative rotation with respect thereto, said rotor having at least one tapering recess, heads for said casing, at least one of which is provided with a tapering portion to extend into said recess, one or both of said heads and said rotor each having a passage or passages therein for the reception of a motive agent and adapted to register during the relative rotation of said casing and rotor, and means for maintaining a tight fit between the registering mouths of said passages. 80
24. A rotary engine comprising a casing, a shaft having a rotor thereon and positioned within said casing for relative rotation with respect thereto, heads for said casing, one or both of said heads having associated therewith a tapering portion adapted to extend into said rotor, and provisions for introducing a plurality of motive agents through either or both of said tapering portions. 85
25. A rotary engine comprising a casing, a shaft having a rotor thereon and positioned within said casing for relative rotation with respect thereto, heads for said casing, one or both of said heads having associated therewith a tapering portion adapted to extend into said rotor, and provisions for introducing a plurality of motive agents through either or both of said tapering portions into said rotor for discharge therefrom into said casing. 90
26. A rotary engine comprising a casing, a shaft having a rotor thereon and positioned within said casing for relative rotation with respect thereto, heads for said casing, one or both of said heads having associated therewith a tapering portion adapted to extend into said rotor, and provisions for introducing a plurality of motive agents through either or both of said tapering portions into said casing and engaging with said rotor, means for maintaining a tight fit between said portion or portions and said rotor, and means for introducing a plurality of motive agents through one or both of said portions into the interior of said casing. 95
27. A rotary engine comprising a casing, a shaft having a rotor thereon and positioned within said casing for relative rotation with respect thereto, heads for said casing, one or both of said heads having associated therewith a tapering portion adapted to extend into said rotor, provisions for introducing a plurality of motive agents through either or both of said tapering portions, and means for mixing said agents in one or both of said tapering portions. 100
28. A rotary engine comprising a casing, a shaft having a rotor thereon and positioned within said casing for relative rotation with respect thereto, heads for said casing, one or both of said heads having associated therewith a tapering portion adapted to extend into said rotor, provisions for introducing a plurality of motive agents through either or both of said tapering portions, and means for spraying one of said agents by another. 105
29. A rotary engine comprising a casing, a shaft having a rotor thereon and positioned within said casing for relative rotation with respect thereto, heads for said casing, one or both of said heads having associated therewith a tapering portion adapted to extend into said rotor, provisions for introducing a plurality of motive agents through either or both of said tapering portions, and means for spraying one of said agents by another within one or both of said tapering portions. 110
30. A rotary engine comprising a casing, a shaft having a rotor thereon and positioned within said casing for relative rotation with respect thereto, heads for said casing, one or both of said heads having associated therewith a tapering portion adapted to extend into said rotor, means for spraying one or more of said agents and provisions for introducing such agents into the rotor. 115
31. A rotary engine comprising a casing, a shaft having a rotor thereon and positioned within said casing for relative rotation with respect thereto, heads for said casing, one or both of said heads having a portion extending into said casing and engaging with said rotor, means for maintaining a tight fit between said portion or portions and said rotor, and means for introducing a plurality of motive agents through one or both of said portions into the interior of said casing. 120
32. A rotary engine comprising a casing, a shaft having a rotor thereon and positioned within said casing for relative rotation with respect thereto, heads for said casing, one or both of said heads having a portion extending into said casing and engag- 125
- ing, one or both of said heads having asso- 130

- ing with said rotor, means for maintaining a tight fit between said portion or portions and said rotor, and means for introducing a plurality of motive agents into said rotor to 5 be discharged therefrom into said casing.
33. A rotary engine comprising a casing, a shaft having a rotor thereon and positioned within said casing for relative rotation with respect thereto, heads secured to 10 said casing, a tapering portion or portions surrounding said shaft and separate from said heads, the end face or faces of said rotor being correspondingly tapered to receive said tapering portion or portions, said 15 tapering portion or portions having an encircling rim or rims, and means carried thereby to adjust said portion or portions axially of said shaft to take up wear between them and said rotor.
34. A rotary engine comprising a casing, a shaft having a rotor thereon and positioned within said casing for relative rotation with respect thereto, heads secured to 20 said casing, a tapering portion or portions surrounding said shaft and separate from said heads, the end face or faces of said rotor being correspondingly tapered to receive 25 said tapering portion or portions, said tapering portion or portions having an encircling rim or rims, and means carried 30 thereby to adjust said portion or portions axially of said shaft to take up wear between them and said rotor and to limit the extent of movement of said portion or portions 35 toward said rotor.
35. A rotary engine comprising a casing, a shaft having a rotor thereon and positioned within said casing for relative rotation with respect thereto, said rotor having 40 a passage or passages therein for the introduction of a motive agent or agents into said casing, heads for said casing having means for securing them thereto and a passage or 45 passages for introducing a motive agent or agents through one or both of said heads into 50 said passage or passages in the rotor, and means for circumferentially varying the point of registration of said passage or 55 passages in said head or heads with said passage or 60 passages in said rotor.
36. A rotary engine comprising a casing, a shaft having a rotor thereon and positioned with said casing for relative rotation with respect thereto, said rotor having a 65 passage or passages therein for the introduction of a motive agent or agents into said casing, heads for said casing having means for securing them thereto, a bearing or bearings intermediate one or both of said heads and 70 said shaft and having a passage or passages 75 therein for the introduction of a motive agent or agents, said rotor having a passage or 80 passages therein adapted to register with the passage or passages in said bearing or 85 bearings, and means to adjust said bearing

or bearings circumferentially of said shaft to vary the point of admission of the motive agent or agents into said rotor.

37. A rotary engine comprising a casing, a shaft having a rotor thereon and positioned within said casing for relative rotation with respect thereto, said rotor having a passage or passages therein for the introduction of a motive agent or agents into said 70 casing, heads for said casing having means for securing them thereto, a tapering portion interposed between said shaft and one or both of said heads and provided with a passage or passages for the introduction of a 75 motive agent or agents, said rotor having a 80 passage or passages therein adapted to register with the passage or passages in said tapering portion or portions and a recess or 85 recesses for said tapering portion or portions, and means to adjust said tapering portion or portions circumferentially of the shaft to vary the point of admission of said agent or agents into said rotor.

38. A rotary engine comprising a casing, a shaft having a rotor thereon and positioned within said casing for relative rotation with respect thereto, said rotor having a passage or passages therein for the introduction of a motive agent or agents into said 90 casing, heads for said casing, and means for securing them thereto, one or both of said heads having a passage or passages therein for the introduction of a motive agent or agents into said 95 rotor when the engine is operative in one direction and a separate 100 passage or passages therein for the introduction of a motive agent or agents when the engine is operative in the opposite direction.

39. A rotary engine comprising a casing, a shaft having a rotor thereon and positioned within said casing for relative rotation with respect thereto, said rotor having a passage or passages therein for the introduction of a motive agent or agents into said 100 casing, heads for said casing, and means for securing them thereto, one or both of said heads having a passage or passages therein for the introduction of a motive agent or agents into said 110 rotor when the engine is operative in one direction and a separate passage or passages therein for the introduction of a motive agent or agents when the engine is operative in the opposite direction, and means to render inoperative either of 111 120 said passages in said head or heads.

40. A rotary engine comprising a casing, a shaft having a rotor thereon and positioned within said casing for relative rotation with respect thereto, said rotor having 125 a passage or passages therein for the introduction of motive agent or agents into said casing, heads for said casing having means for securing them thereto, a bearing or bearings intermediate said head or heads and the

shaft, said head or heads having a passage or passages therein for the introduction of a motive agent or agents into said rotor when the engine is operative in one direction 5 and a separate passage or passages therein for the introduction of a motive agent or agents when the engine is operative in the opposite direction.

41. A rotary engine comprising a casing, 10 a shaft having a rotor thereon and positioned within said casing for relative rotation with respect thereto, said rotor having a passage or passages therein for the introduction of a motive agent or agents into said 15 casing, heads for said casing having means for securing them thereto, a tapering portion or portions intermediate said head or heads and said shaft and having a passage or passages therein for the introduction of 20 a motive agent or agents into said rotor when the engine is operative in one direction and a separate passage or passages therein for the introduction of a motive agent or agents when the engine is operative 25 in the opposite direction.

42. A rotary engine comprising a shaft having a rotor thereon and positioned within said casing for relative rotation with respect thereto, said rotor having a passage or 30 passages therein for the introduction of a motive agent or agents into said casing, heads for said casing having means for securing them thereto, a bearing or bearings intermediate said head or heads and the 35 shaft having means for securing a tight fit between the same and said rotor, said bearing or bearings having a passage or passages therein for the introduction of a motive agent or agents into said rotor when the 40 engine is operative in one direction and a separate passage or passages therein for the introduction of motive agent or agents when the engine is operative in the opposite direction, and means to render inoperative either 45 of said passages in said bearing or bearings.

43. A rotary engine comprising a casing, a shaft having a rotor thereon and positioned within said casing for relative rotation with respect thereto, heads for said casing, 50 one or both of said heads having associated therewith a tapering portion adapted to extend into the said rotor, provisions for introducing a plurality of motive agents through either or both of said tapering portions, and means whereby the plurality of 55 motive agents may be separately introduced through either or both of said tapering portions into the rotor, or whereby said plurality of motive agents may be mixed in 60 either or both of said tapering portions.

44. A rotary engine comprising a casing, a shaft having a rotor thereon and positioned within said casing for relative rotation with respect thereto, heads for said cas-

ing, one or both of said heads having associated therewith a tapering portion adapted to extend into said rotor, one or both of said tapering portions having a plurality of chambers therein for the admission of a plurality of motive agents, and a valve permitting the mixture of said motive agents within the tapering portion. 65

45. A rotary engine comprising a casing, a shaft having a rotor thereon and mounted for relative rotation with respect to said casing, heads for said casing, a bearing interposed between one or both of said heads and said shaft, one of said parts, namely—a bearing and said rotor, being tapered and the other of said parts being correspondingly recessed to receive such tapered part, and means to move such bearing or bearings axially of the shaft to take up wear. 75

46. A rotary engine comprising a casing, a shaft having a rotor thereon and mounted for relative rotation with respect to said casing, heads for said casing, a bearing interposed between one or both of said heads and said shaft, one of said parts, namely—a bearing and said rotor, being tapered and the other of said parts being correspondingly recessed to receive said tapered part, means to move such bearing or bearings axially of the shaft to take up wear, and means for introducing a motive agent or agents through either or both of said bearings into said rotor. 80

47. A rotary engine comprising a casing, a shaft having a rotor thereon and positioned within said casing for relative rotation with respect thereto, said rotor having a passage or passages therein for the introduction of a motive agent or agents into said casing, heads for said casing having means for securing them thereto, a bearing interposed between said shaft and one or both of said heads and provided with a passage or passages for the introduction of a motive agent or agents, said rotor having a passage or passages therein adapted to register with the passage or passages in said bearing or bearings, one of said parts, namely—said bearing or bearings and said rotor, being recessed and the other part being correspondingly tapered to extend into said recess, means to adjust said bearing or bearings circumferentially of the shaft to vary the point of admission of said agent or agents into the rotor, and means axially to move said bearing or bearings to take up wear. 105

48. A rotary engine comprising a casing, a shaft having a rotor thereon and positioned within said casing for relative rotation with respect thereto, said rotor having a passage or passages therein for the introduction of a motive agent or agents into said casing, heads for said casing having means for securing them thereto, means for intro-

- ducing a motive agent or agents through one or both of said heads into said rotor passage or passages, and means to prevent back firing through said passage or passages.
5. 49. A rotary engine comprising a casing, a shaft having a rotor thereon and positioned within said casing for relative rotation with respect thereto, said rotor having a passage or passages therein for the introduction of a motive agent or agents into said casing, heads for said casing having means for securing them thereto, means for introducing a motive agent or agents through one or both of said heads into said rotor passage or passages, and a check valve for preventing back firing in said passage or passages.
50. A rotary engine comprising a casing, a shaft, a rotor thereon and positioned within said casing for relative rotation with respect thereto, a head or heads secured to said casing and a tapering portion or portions surrounding said shaft and extending into said rotor and having an inner terminal face, there being a space between said face or faces and the adjacent face or faces of the rotor, permitting the axial adjustment of said tapering portion or portions and means to admit a motive agent through at least one of said heads into said rotor.
51. A rotary engine comprising a casing, a shaft having a rotor thereon and positioned within said casing for relative rotation with respect thereto, an abutment having an in and out movement with respect to said rotor, and a head or heads secured to said casing, one of said parts, namely, said head or heads and said rotor, having a tapering portion or portions surrounding the shaft and extending into the other, there being a space between the inner end of said tapering portion or portions and the adjacent face of the other part, thereby permitting axial adjustment.
52. A rotary engine comprising a casing, a shaft having a rotor thereon and positioned within said casing for relative rotation with respect thereto, heads for said casing, one or both of said heads having associated therewith a tapering portion adapted to extend into said rotor, and provisions for introducing an explosive agent through either or both of said tapering portions.
53. A rotary engine comprising a casing, a shaft having a rotor thereon and positioned within said casing for relative rotation with respect thereto, said rotor having a passage or passages for the introduction of a motive agent or agents into said casing, heads for said casing having means for securing them thereto, a bearing or bearings interposed between said shaft and said head or heads, a plurality of passages in one or both of said bearings for the introduction of a plurality of motive agents, and a check valve in one or both of said bearings for preventing back firing and for assisting the admixture of said agents.
54. A rotary engine comprising a casing and a relatively rotatable rotor mounted therein and having a passage or passages for the admission of a motive agent or agents and a tapering recess at one or both ends, one or more heads for said casing, one at least of which has a corresponding tapered projection, means for taking up wear between said head or heads and said rotor, and means for admitting a motive agent or agents through one or both of said heads into said passage or passages in the rotor.
55. A rotary engine comprising a casing and a relatively rotatable rotor mounted therein and having a passage or passages for the admission of a motive agent or agents, one at least of which has a corresponding tapered projection, one or more heads for said casing, means for taking up wear between said head or heads and said rotor, means for admitting a motive agent or agents through one or both of said heads into said passage or passages in the rotor, and means for controlling the admission of the motive agent or agents through said passage or passages.
56. A rotary engine comprising a casing and a relatively rotatable rotor mounted therein and having a passage or passages for the admission of a motive agent or agents, one or more heads for said casing, means for admitting a motive agent or agents through one or both of said heads into said passage or passages in the rotor, and means within said head or heads to regulate the admission of such motive agent or agents through said passage or passages.
57. A rotary engine comprising a casing and a relatively rotatable rotor mounted therein and having a passage or passages for the introduction of a motive agent or agents, one or more heads for said casing and means for securing them thereto, one or both of said heads having a passage or passages therein for the introduction of a motive agent or agents into said passage or passages in said rotor, and means intermediate the rotor and the outer faces of said head or heads to regulate the admission of the motive agent or agents through said passage or passages.
58. A rotary engine comprising a casing and a relatively rotatable rotor mounted therein and having a passage or passages for the introduction of a motive agent or agents, a head or heads for said casing having means for securing them thereto, one or both of said heads having a passage or passages therein for the introduction of a motive agent or agents into said passage or

passages in said rotor, and means interposed between the adjacent faces of said rotor and said heads or heads for controlling the admission of a motive agent or agents into said passage or passages in said rotor.

5. 59. A rotary engine comprising a casing, a shaft having a rotor thereon and positioned within said casing for relative rotation with respect thereto, said rotor having a passage or passages therein for the introduction of a motive agent or agents into said casing, a head or heads for said casing, and means for securing them thereto, one or both of said heads having a passage or passages therein for the introduction of a motive agent or agents into said rotor passage or passages, and circumferentially movable means for reversing the engine by controlling the admission of the motive agent or agents through the passage or passages in the rotor.

60. A rotary engine comprising a casing, a shaft having a rotor thereon and positioned within said casing for relative rotation with respect thereto, said rotor having a passage or passages therein for the introduction of a motive agent or agents into said casing, a head or heads for said casing, and means for securing them thereto, one or both of said heads having a passage or passages therein for the introduction of a motive agent or agents into said rotor passage or passages, and means intermediate the adjacent faces of said rotor and head or heads for reversing the engine.

61. A rotary engine comprising a casing, a shaft having a rotor thereon and positioned within said casing for relative rotation with respect thereto, said rotor having a passage or passages therein for the introduction of a motive agent or agents into said casing, a head or heads for said casing, and valve means intermediate the adjacent faces of said rotor and head or heads for reversing the engine.

62. A rotary engine comprising a casing, a shaft having a rotor thereon and positioned within said casing for relative rotation with respect thereto, said rotor having a passage or passages therein for the introduction of the motive agent or agents into said casing, heads for said casing, means for admitting a motive agent or agents through one or both of said heads into said passage or passages in the rotor, and valve means intermediate the adjacent faces of said rotor and said head or heads for reversing the engine.

63. A rotary engine comprising a casing, a shaft having a rotor thereon and positioned within said casing for relative rotation with respect thereto, said rotor having a passage or passages therein for the introduction of a motive agent or agents into said casing, heads for said casing having

means for securing them thereto, means for admitting a motive agent or agents through one or both of said heads into said passage or passages in the rotor, and a ring valve or valves interposed between the adjacent faces of said rotor and one or both of said heads for reversing the engine.

64. A rotary engine comprising a casing, a shaft having a rotor thereon and positioned for relative rotation with respect thereto, said rotor having a passage or passages therein for the introduction of a motive agent or agents into said casing, heads for said casing, a bearing or bearings interposed between said shaft and said head or heads, one of said parts, namely—said bearing or bearings and said rotor, being tapered and the other part being correspondingly recessed to receive such tapered portion, said bearing or bearings having a passage or passages therein for the introduction of a motive agent or agents into the passage or passages of said rotor, and means intermediate the adjacent faces of said rotor and said bearing or bearings for reversing the engine.

65. A rotary engine comprising a casing and a relatively rotatable rotor mounted therein, said rotor having a passage or passages therein for the introduction of the motive agent or agents into said rotor, provisions for introducing such agent or agents into said passage or passages, said passage or passages in the rotor being provided with a salient portion to receive the impact of the incoming agent or agents.

66. A rotary engine comprising a casing and a relatively rotatable rotor mounted therein, heads for said casing, one or more passages in said rotor for the introduction of a motive agent or agents thereinto, provisions for introducing a motive agent or agents in said passage or passages, one or more of said passages in the rotor having a deflected portion providing an impact receiving surface.

67. A rotary engine comprising a casing, a shaft having a rotor thereon and positioned within said casing for relative rotation with respect thereto, heads for said casing, one of said parts, namely, said head or heads and said rotor, having a tapering portion or portions adapted to extend into the other, and provisions for introducing an explosive agent through either or both of said tapering portions.

68. A rotary engine comprising a casing, a shaft having a rotor and positioned within said casing for relative rotation with respect thereto, heads for said casing, one or both of said heads having associated therewith a tapering portion adapted to extend into said rotor, and means to spray a motive agent introduced through one or both of said tapering portions.

69. A rotary engine comprising a casing and a relatively rotatable rotor mounted therein, heads for said casing, means for introducing a plurality of motive agents through said casing and through said rotor into the combustion chamber, and means positioned in the wall of said casing to prevent back firing and to assist the admixing of said agents. 70
- 10 70. A rotary engine comprising a casing having an offset chamber and a rotor within the casing, constructed and arranged to contact with the peripheral wall of said casing, the peripheral-wall contacting portion of the rotor acting as a valve to close said chamber, and thereby to constitute a separate combustion chamber. 75
- 15 71. A rotary engine comprising a casing, a shaft having a rotor thereon and positioned within said casing for relative rotation with respect thereto, heads for said casing, some of said parts, namely, one or both of said heads and said rotor, having a tapering portion to extend into the other, and means to spray a motive agent introduced through one or both of said tapering portions. 80
- 20 72. A rotary engine comprising in combination a casing, a rotor therein, an admission port controlled by the rotor, the relative proportions of the rotor and admission port being such as to permit in its rotation scavenging at one side the rotor, then the closing of the port with subsequent filling and firing, and finally the admission of the motive agent to the opposite side of the rotor for motive power. 85
- 25 73. A rotary engine comprising a casing and a relatively rotatable rotor mounted therein, heads for said casing, one or both of said heads having a tapering portion extending into the rotor, a mixing chamber within one or both of said tapering portions, means for introducing a plurality of motive agents into said mixing chamber or chambers, and means for delivering said mixed motive agents into the combustion chamber. 90
- 30 74. A rotary engine comprising a casing and a relatively rotatable rotor mounted therein, heads for said casing, an explosion chamber within said casing, for conducting a plurality of unmixed motive agents to and for mixing them within said explosion chamber. 95
- 35 75. A rotary engine having a casing, a shaft having a rotor thereon and positioned within said casing for relative rotation with respect thereto, said rotor having a passage or passages therein for the introduction of a motive agent or agents into said casing, heads for said casing, one or both of said heads having a passage or passages therein for the introduction of a motive agent or agents into said rotor when the engine is operative in one direction, and a separate 100
- 40 passage or passages therein for the introduction of a motive agent or agents into said rotor when the engine is operative in the other direction, and means to render inoperative either the passage or passages in the head or rotor. 105
- 45 76. A rotary engine comprising a casing and a relatively rotatable rotor mounted therein, heads for said casing, means for admitting a motive agent or agents through the rotor into the combustion chamber and a balanced, safety spring pressed valve for controlling the admission of the motive agent or agents into the combustion chamber, and held closed by the explosion. 110
- 50 77. A rotary engine comprising a casing and a relatively rotatable rotor mounted therein, heads for said casing, means for introducing a motive agent or agents through the rotor into the combustion chamber and a differential valve controlling the admission of the motive agent or agents, the diameter of the head of the valve being in excess of the remainder thereof. 115
- 55 78. A rotary engine comprising a casing and a relatively rotatable rotor mounted therein, heads for said casing, means for admitting a motive agent or agents into the combustion chamber, and a balanced valve separately controlling the admission of said agent or agents thereinto and closed by increased pressure in the combustion chamber. 120
- 60 79. A rotary engine comprising a casing and a relative rotatable rotor mounted therein, heads for said casing, means for mixing a plurality of motive agents, and a valve governing the admission of the motive agent or agents and adapted to open in the event of back firing. 125
- 65 80. A rotary engine comprising a casing and a relatively rotatable rotor mounted therein, heads for said casing, means for introducing a motive agent through the rotor into the casing, means for mixing a plurality of motive agents, a valve governing the admission of the motive agents, and means for regulating said valve, whereby it may open at any predetermined pressure. 130
- 70 81. A rotary engine comprising a casing and a relatively rotatable rotor mounted therein, heads for said casing, a mixing chamber into which a plurality of motive agents may be introduced and a valve interposed between said mixing chamber and the combustion chamber, said valve being adapted to open in the event of explosion back of said valve. 135
- 75 82. A rotary engine comprising a casing and a relatively rotatable rotor mounted therein, heads for said casing, a mixing chamber within the casing, passages for separately admitting a plurality of motive agents into said mixing chamber, and a valve interposed between said mixing chamber and the combustion chamber, said valve 140

being constructed to open in the event of excess pressure.

83. A rotary engine comprising a casing, a combustion chamber within the casing and a relatively rotatable rotor mounted therein, heads for said casing, means for admitting a motive agent to the combustion chamber, a valve controlling the admission of such agent, and a plurality of passages admitting 10 a second motive agent through the valve seat of said valve, whereby a thorough admixture of said agents is effected.

84. A rotary engine comprising a casing, a combustion chamber within the casing and 15 a relatively rotatable rotor mounted therein, heads for said casing, a passage for admitting a motive agent to the combustion chamber, a valve controlling the admission of such agent through said passage, an annular 20 chamber surrounding said passage, to which a second motive agent may be supplied, and a plurality of passages leading from said annular chamber under the valve seat, whereby the second motive agent may be 25 thoroughly intermixed with the first.

85. A rotary engine comprising a casing and a relatively rotatable rotor mounted therein, heads for said casing, a passage for admitting a motive agent to the combustion 30 chamber, a valve controlling the admission of such agent through said passage, an annular chamber surrounding said passage, to which a second motive agent may be supplied, and a plurality of passages leading 35 from said annular chamber under the valve seat, whereby the second motive agent may be thoroughly intermixed with the first, and means for regulating the admission of the second motive agent through said passages.

86. A rotary engine comprising a casing and a relatively rotatable rotor mounted therein, heads for said casing, means for admitting the motive agent or agents to the combustion chamber, a valve for controlling 40 such admission, mechanical means for periodically opening said valve, and a single means for controlling the elevation of said valve, its time of opening and closing and length of opening, said means effecting all 45 gradations of adjustment of said valve through a given range of movement.

87. A rotary engine comprising a casing, and a relatively rotatable rotor mounted therein, heads for said casing, a mixing 50 chamber, a valve interposed between said mixing chamber and the combustion chamber, a check valve anterior to said mixing chamber, and means for mixing said agents by the opening of said check valve.

88. A rotary engine comprising a casing and a relatively rotatable rotor mounted therein, heads for said casing, means for admitting a motive agent to the combustion chamber, a check valve for controlling the 55 inward passage of the motive agent, and a

plurality of passages for introducing a second motive agent beneath the seat of the check valve, whereby an intermixing of the two agents is effected.

89. A rotary engine comprising a casing, 70 and a relatively rotatable rotor mounted therein, heads for said casing, a compression chamber, means for admitting a motive agent or agents to the compression chamber, a balanced valve for controlling the admission of such agent or agents, and a removable plug at the opposite side of the compression chamber from the valve head, upon removal of which access is afforded to the 75 valve.

90. A rotary engine comprising a casing and a relatively rotatable rotor mounted therein, heads for said casing, means for admitting a motive agent to the combustion chamber, a balanced valve for controlling the admission of such agent, a removable seat for said valve and means for admitting a second motive agent under said valve seat.

91. A rotary engine comprising a casing and a relatively rotatable rotor mounted 90 therein, heads for said casing, an explosion chamber within the casing, means for admitting a plurality of motive agents separately to the explosion chamber and for mixing them therein, a balanced safety valve 95 controlling such admission and mixing, and mechanical means for periodically opening said valve.

92. A rotary engine comprising a casing and a relatively rotatable rotor mounted 100 therein, heads for said casing, means for admitting a motive agent or agents to the combustion chamber, a valve controlling such admission, mechanical means for periodically opening said valve and means for regulating the period of lift and degree of elevation of the valve for all gradations of adjustment throughout a given range of movement.

93. A rotary engine comprising a casing and a relatively rotatable rotor mounted 110 therein, heads for said casing, an abutment mounted for co-operation with said rotor and having a channel upon its contact face to hold the lubricant and to effect an equal 115 distribution thereof, and means for supplying lubricant to said channel.

94. A rotary engine comprising a casing and a relatively rotatable rotor mounted 120 therein, heads for said casing, the casing chamber being provided between said heads with an outward parallel wall extension narrow in the direction of the incoming agent or agents, and a balanced valve for admitting one or more motive agents to such extension.

95. A rotary engine comprising a casing and a relatively rotatable rotor mounted 130 therein, heads for said casing, the casing chamber having between said heads an out-

- ward parallel walled extension narrow in the direction of the incoming agents to facilitate scavenging, and a balanced valve for admitting a motive agent or agents to said chamber.
96. A rotary engine comprising a casing and a relatively rotatable rotor mounted therein, heads for said casing, the casing chamber being provided between said head 10 with a substantially radial parallel walled extension rounded at the entrance end and narrow in the direction of the incoming agent or agents, and a balanced admission valve opening in said chamber.
97. A rotary engine comprising a casing, a rotor therein, and a chamber in said casing periodically closed by said rotor to permit the filling of said chamber and ignition and the subsequent admission past said rotor 20 into the casing.
98. A rotary engine comprising a cylindrical casing, heads at the ends thereof, said cylinder having an offset chamber outwardly extending between said heads and a rotor 25 within the casing having a cylinder contacting portion acting as a valve to close said chamber.
99. A rotary engine comprising a casing, heads therefor, a rotor in said casing, a shaft 30 therefor, and means to admit motive fluid into the rotor at opposite sides of the rotor and at opposite sides of the shaft to equalize the pressure between the rotor and the heads.
100. A rotary engine comprising a casing, 35 a rotor therein, one or more spoked abutments contacting with said rotor, means to pass a temperature regulating agent through said spoke or spokes and means to introduce a cushioning agent behind said abutment.
101. A rotary engine comprising a casing 40 and a rotor mounted therein for rotation, heads for said casing, a port of substantially the width of said rotor and periodically closed by said rotor for admitting a motive agent or agents into said casing, said casing being shaped adjacent the point of admission to direct the motive energy toward that portion of the rotor that is of the greatest radial extent.
102. A rotary engine comprising a casing 45 having a combustion chamber and a relatively rotatable rotor mounted therein, heads for said casing, means for admitting a motive agent or agents to the combustion chamber, said casing being provided adjacent such point of admission with a recessed flattened portion belled on both sides.
103. A rotary engine comprising a casing 50 having a combustion chamber and a relatively rotatable rotor mounted therein, heads for said casing, means for admitting a motive agent or agents through the rotor into the combustion chamber, and means for admitting a motive agent or agents into said combustion chamber exterior to the rotor to provide a succession of impulses or ignitions for one and the same combustion chamber.
104. A rotary engine comprising a casing having a combustion chamber and a relatively rotatable rotor mounted therein, heads 70 for said casing, means for admitting the motive agent or agents through the rotor into the combustion chamber, and means for admitting the motive agent or agents at the same time through the casing into the combustion chamber to provide a succession of impulses or ignitions for one and the same combustion chamber.
105. A rotary engine comprising a casing having a combustion chamber and a relatively rotatable rotor mounted therein, heads 80 for said casing, a passage in said rotor for admitting a motive agent or agents into the combustion chamber, the mouth of said passage at the periphery of the rotor being cut 85 away at the rear thereof, whereby the leading wall of the passage presents an impact receiving shoulder.
106. A rotary engine comprising a casing, a rotor therein, and an abutment adapted 90 to engage the rotor, a chamber in the rear of the abutment, and connections to the exhaust to admit the exhaust of the motive fluid to the rear of the abutment, thereby to press said abutment toward the rotor.
107. A rotary engine comprising a casing, 95 a relatively rotatable rotor mounted therein, said casing being recessed, an abutment mounted within said recess and movable toward and from the center of the rotor, and means to force said abutment radially inward, said means including an abutment face extending beyond the radial line from the center of rotation of the rotor to the leading edge of the recess wherein the abutment is mounted.
108. A rotary engine comprising a casing, 100 a rotor therein, an abutment adapted to engage the rotor, a chamber in the rear of the abutment and a connection between said chamber and the exhaust for the reception of the exhaust gases, whereby said exhaust gases act to press the abutment toward the rotor.
109. A rotary engine comprising a casing, 105 a rotor therein, an abutment adapted to engage the rotor, a chamber between the abutment and casing and independent of the admission port to admit motive fluid to the abutment to force it into engagement with the rotor, and means for effecting admission of said motive agent to the abutment chamber at a time to effect such engagement prior to the admission of motive fluid to the working face of the rotor and a regulating valve 110 in the casing adjacent said abutment to vary the pressure of the fluid in said chamber.
110. A rotary engine comprising a casing 115 and a relatively rotatable rotor, an abutment mounted for engagement with the periph-

eral surface of the rotor and provided with a wearing shoe, having a two line contact and means for introducing a lubricant to the surface of said shoe for substantially 5 its entire width.

111. A rotary engine comprising a casing and a relatively rotatable rotor, an abutment mounted for engagement with the peripheral surface of said rotor and having a 10 wearing shoe, and means for introducing a lubricant between the abutment and shoe.

112. A rotary engine comprising a casing and a relatively rotatable rotor mounted therein, said rotor having a pair of opposed 15 concentric portions and another concentric portion at a greater radial distance, said casing being recessed at the point of admission of the motive agent or agents into the chamber to provide an enlargement, the 20 last mentioned concentric portion of the rotor being not less in extent than the cross section of the enlargement in the direction circumferentially of the rotor whereby said enlargement is periodically closed by said 25 defined portion of the rotor which is of greatest radial extent.

113. A rotary engine comprising a casing and a relatively rotatable rotor mounted therein, heads for said casing, said rotor being provided upon that portion of its peripheral surface contacting with the casing and upon the adjacent portion of its end faces contacting with the heads with a packing strip composed of two members, each of 30 which extends along one end face of the rotor and thence at an angle along the said peripheral portion of the rotor, and an interposed member, the adjacent faces of said members being inclined, whereby a tight 35 joint is maintained, and means tending normally to force said members radially outward toward the casing and heads.

114. A rotary explosion engine comprising a casing and a relatively rotatable rotor 45 mounted therein, a spoked abutment movable toward and from the center of said rotor and adapted to contact with the peripheral surface thereof, means for admitting the motive agent or agents to the 50 explosion chamber, and provisions for exhausting the motive agent or agents about a spoke in said abutment.

115. A rotary engine comprising a casing and a relatively rotatable rotor mounted 55 therein, heads for said casing, an abutment mounted for pivotal movement in said casing and adapted to contact with said heads, packing in said heads for the pivotal portion of the abutment and packing between 60 the abutment and the casing.

116. An internal combustion engine comprising a casing and a relatively rotatable rotor mounted therein, heads for said casing and one or more pivoted abutments 65 mounted for movement toward and from the

center of rotation of said rotor, said abutment or abutments having two operative portions and self-adjusting shoes each having two line contacts with the rotor.

117. A rotary engine comprising a casing 70 and a rotor mounted therein, a movable abutment, a compression chamber for exhaust gases behind said abutment, and means for admitting said exhaust gases to said chamber, thereby to force said abut- 75 ment inward.

118. A rotary engine comprising a casing, a rotor therein and heads distinct from but secured to said casing, said rotor and heads 80 constituting parts, one of which has a portion at each side of the rotor extending into an adjoining one of said parts, thereby to center the rotor, and means to vary the inward extension of such portion.

119. A rotary engine comprising a casing 85 and a relatively rotatable rotor mounted therein, heads for said casing, one or more abutments adapted to coöperate with said rotor and casing, means for taking up wear between the abutment or abutments and heads, and means to admit a motive agent behind the abutment or abutments, thereby to effect inward pressure of said abutment or abutments.

120. A rotary engine comprising a casing 95 and a relatively rotatable rotor mounted therein, heads for said casing, one or more abutments in said casing and adapted operatively to engage the rotor, means for taking up wear between the abutment or abutments and heads, and means to admit a motive agent behind the abutment or abutments, thereby to effect inward pressure of said abutment or abutments.

121. A rotary engine comprising a casing 105 and a relatively rotatable rotor mounted therein, head ends for said casing, one or more abutments in said casing and adapted to operatively engage the rotor, and annular packing strips for taking up wear between the side faces of the abutment or abutments and said head ends, one or more of said abutments having means to permit the exhaust past the same.

122. A rotary engine comprising a casing 115 and a relatively rotatable rotor mounted therein, head ends for said casing, one or more abutments mounted to coöperate with said rotor and casing, split packing rings to take up wear between the side faces of the abutment or abutments and said head ends, and means permitting the exhaust to pass in contact with said abutment or abutments to the rear thereof.

123. A rotary engine comprising a casing 125 and a relatively rotatable rotor mounted therein, a compression chamber extending into the casing and directly communicating with the space between the casing and rotor, heads for said casing, one or more to 130

- and from movable abutments mounted to co-operate with said rotor and said casing, means to introduce a temperature regulating agent into said abutment or abutments, and
- 5 means permitting the exhaust to pass in contact with said abutment or abutments to the rear thereof.
124. A rotary engine comprising a casing and a relatively rotatable rotor mounted therein, means to introduce motive agents through the casing and through the rotor into the space between the casing and rotor, heads for said casing, one or more abutments mounted to co-operate with said rotor
- 10 and said casing, means to introduce a temperature regulating agent into said abutment or abutments, means permitting the exhaust to pass in contact with said abutment or abutments to the rear thereof, and
- 15 20 means for taking up wear between the abutment or abutments and heads.
125. A rotary engine comprising a casing and a relatively rotatable rotor mounted therein, a compression chamber in the casing positioned to discharge a motive agent direct therefrom to the space between the casing and rotor, heads for said casing, one or more abutments mounted for operative engagement with said rotor and said casing,
- 25 30 means for introducing a temperature regulating agent into said abutment or abutments, and means for taking up wear between the abutment or abutments and heads.
126. A rotary engine comprising a casing and a relatively rotatable rotor mounted therein, heads for said casing, and one or more abutments mounted to engage the peripheral surface of said rotor, the leading face of the rotor contacting portion of the
- 35 40 abutment or abutments being circumferentially advanced, the motive agent or agents acting only upon the leading face, thereby to force the abutment or abutments toward the rotor.
- 45 127. A rotary engine comprising a casing and a relatively rotatable rotor mounted therein, heads for said casing, said casing being recessed, one or more abutments mounted within said recess or recesses in said casing and adapted to move toward and from the center of the rotor, a compression chamber or chambers 113 co-operating with said abutment or abutments, said chamber or chambers 113 being so positioned as to be in open communication with the space between the casing and rotor when the corresponding abutment is moved inwardly, the leading face of said abutment being advanced beyond the radial line from the center of rotation of the rotor to the leading edge of the recess wherein such abutment is mounted.
- 50 55 60 65 128. A rotary engine comprising a casing and a relatively rotatable rotor mounted therein, heads for said casing, one or more abutments mounted for co-operation with said rotor and said casing, and means for introducing fluid pressure other than the unused working fluid to the rear of said abutment or abutments to force the same into operative position.
129. A rotary engine comprising a casing and a relatively rotatable rotor mounted therein, heads for said casing, one or more abutments mounted in said casing and adapted to engage the peripheral surface of said rotor, and means for introducing fluid pressure other than the unused working fluid to the rear of said abutment or abutments to force the same into operative position.
130. A rotary engine comprising a casing and a relatively rotatable motor mounted therein, heads for said casing, one or more abutments mounted in said casing and adapted to engage the peripheral surface of said rotor, means permitting the exhaust of the motive agent or agents in contact with said abutment or abutments to the rear thereof, a recess being formed between the rear of said abutment or abutments and the casing to permit the exhaust to act upon the abutment or abutments and move it toward the rotor.
131. A rotary engine comprising a casing and a relatively rotatable rotor mounted therein, heads for said casing, an abutment mounted in a recess in said casing and having its face depressed from the inner face of said casing, a compression chamber co-acting with said abutment, and means permitting the exhaust of the motive agent or agents in contact with said abutment to the rear thereof.
132. A rotary engine comprising a casing and a relatively rotatable rotor mounted therein, heads for said casing, an abutment mounted in a recess in said casing and movable toward and from the center of the rotor, the walls of said recess and abutment being constructed to permit the formation of a compression chamber between the face of the abutment and the casing upon radial movement of the abutment, said compression chamber being periodically in direct open communication with the space between the rotor and casing, and means for introducing a cushioning fluid into said chamber.
133. A rotary engine comprising a casing and a relatively rotatable rotor mounted therein, heads for said casing, an abutment mounted in a recess in said casing and movable toward and from the center of the rotor, the walls of said recess and abutment being constructed to permit the formation of a compression chamber upon outward radial movement of the abutment and to form a part of the walls of the combustion chamber upon inward movement of the abutment, means for introducing a cushioning fluid be-

tween such walls of the abutment and the recess, and means for regulating the degree of compression in said compression chamber.

134. A rotary engine comprising a casing and a relatively rotatable rotor mounted therein, heads for said casing, an abutment mounted in a recess in said casing and movable toward and from the center of the rotor, the walls of said recess and abutment being constructed to permit the formation of a compression chamber upon outward radial movement of the abutment and to form a part of the walls of the combustion chamber upon inward movement of the abutment, means for introducing a cushioning fluid between said walls of the abutment and the recess, and means for regulating the inflow and outflow of such cushioning fluid.

135. A rotary engine comprising a casing and a relatively rotatable rotor mounted therein, heads for said casing, one or more abutments mounted for pivotal movement in said casing toward and from the center of rotation of the rotor, and spring adjustable means, the tension whereof is maintained substantially constantly connected with the abutment or abutments between the pivotal points thereof and its active portion to move said abutment or abutments radially inward.

136. A rotary engine comprising a casing and a relatively rotatable rotor mounted therein, heads for said casing, a one-piece abutment mounted for coöperation with the rotor and the casing, the abutment being provided with a removable but stationary, one piece wearing holder, and a movable shoe directly carried by said holder.

137. A rotary engine comprising a casing, a shaft having a rotor thereon and positioned within said casing for relative rotation with respect thereto, heads for said casing, means for admitting a motive agent or agents through one or both of said heads into said passage or passages in the rotor, the adjacent faces of the rotor and heads being inclined, whereby one protrudes into the other, and an inclined ring valve or valves interposed between the adjacent inclined faces of said rotor and one or both of said heads for regulating the cut off and for reversing the engine.

138. A rotary engine comprising a casing having a combustion chamber and a relatively rotatable casing, contacting rotor mounted therein, heads for said casing, means for admitting a motive agent or agents to the combustion chamber, a valve controlling such admission, mechanical means for periodically opening said valve, and a single means for regulating the degree of elevation of said valve.

139. A rotary engine comprising a casing and a relatively rotatable rotor mounted therein, heads for said casing, one or more

abutments mounted for pivotal movement in said casing toward and from the center of rotation of the rotor and a cam and spring adjustable means connected with the abutment or abutments between the pivotal point thereof and its active portion to move said abutment or abutments radially inward.

140. A rotary engine comprising a casing, heads for said casing, the latter having an offset chamber between the heads and a rotor within the casing, the portion of the rotor contacting with the casing between the heads acting as a valve to close said chamber.

141. A rotary engine comprising a casing and a relatively rotatable rotor mounted therein, heads for said casing, an abutment mounted for coöperation with said rotor, and having a packing chamber upon its contact face, to which a lubricant may be introduced and a rockable packing member mounted in said packing chamber.

142. A rotary engine comprising a casing and a relatively rotatable rotor mounted therein, heads for said casing, an abutment mounted for engagement with the peripheral surface of said rotor, means for introducing a lubricant to the rotor contacting portion of the abutment, the abutment having means to interrupt the lubricant supply.

143. A rotary engine comprising a casing and a relatively rotatable rotor mounted therein, heads for said casing, an abutment mounted in said casing to contact with the peripheral surface of the rotor, said abutment being provided with a two-point rotor contacting portion, and means for introducing a lubricant between said points.

144. A reversible rotary engine comprising a casing and a relatively rotatable rotor mounted therein, heads for said casing, an abutment mounted in said casing and having two rotor contacting portions respectively operative upon forward and reverse movement, and means for supplying a lubricant only to the active portion of the abutment.

145. A rotary engine comprising a casing and a relatively rotatable rotor mounted therein, heads for said casing, an abutment mounted for pivotal movement in said casing and packing in said head or heads for the pivotal portion of the abutment, said abutment being shaped and arranged to permit exhaust through the same past said pivotal portion.

146. A rotary engine comprising a casing and a rotor mounted for relative rotation therein, heads for said casing, an abutment mounted for movement in said casing and adapted to contact with said heads, said abutment being recessed to permit exhaust therethrough, and means for maintaining a tight fit between said head or heads and the contacting portion or portions of the abut-

ment and between the abutment or abutments and the casing.

147. A rotary engine comprising a casing and a rotor mounted for relative rotation therein, heads for said casing, an abutment mounted for movement in said casing and adapted to contact with said heads; means for maintaining a tight fit between said head or heads and the contacting portion or portions of the abutment, means for introducing a lubricant directly between the abutment and the head or heads and directly between the abutment and the casing and packing means at the abutment surfaces by which such lubricant is received.

148. A rotary engine comprising a casing and a relatively rotatable rotor mounted therein, heads for said casing, an abutment mounted for coöperation with the rotor and the casing and a packing interposed between the abutment and the portion of the engine with which it contacts, said packing comprising opposite angular end portions and an intermediate portion, said portions having inclined adjacent ends whereby a tight fit is maintained as the wear is taken up, said portions maintaining a tight fit with the casing contacting portion, and means tending normally to force said portions outward and the end portions lengthwise.

149. A rotary engine comprising a casing and a relatively rotatable rotor mounted therein, heads for said casing, an abutment mounted for coöperation with the rotor and the casing, packing portions upon opposite ends of the abutment, means tending normally to force the same outward, said packing comprising opposite angular end portions and an intermediate portion, said portions having inclined adjacent ends, whereby a tight fit is maintained as the wear is taken up, and means tending normally to force said intermediate portions outward and lengthwise and the end portions lengthwise of the abutment.

150. A rotary engine comprising a casing and a relatively rotatable rotor mounted therein, heads for said casing, an abutment mounted for coöperation with the rotor and the casing, a packing interposed between the abutment and the portion of the engine with which it contacts, said packing comprising opposite end portions and an intermediate portion, said portions having inclined adjacent ends whereby a tight fit is maintained as the wear is taken up, means tending normally to force said portions outward and the end portions lengthwise, and means for introducing a lubricant between said packing portions and the surface or surfaces with which they contact.

151. A rotary engine comprising a casing and a relatively rotatable rotor mounted therein, heads for said casing, an abutment mounted for coöperation with the rotor and

the casing, packing portions upon opposite ends of the abutment, means tending normally to force the same outward, said packing comprising opposite end portions and an intermediate portion, said portions having inclined adjacent ends whereby a tight fit is maintained as the wear is taken up, means tending normally to force said portions outward and the end portions lengthwise, and means for introducing a lubricant between said packing portions and the surface or surfaces with which they contact.

152. A rotary engine comprising a casing having a combustion chamber and a relatively rotatable rotor mounted therein and heads for said casing, an abutment, the combustion chamber being provided with an extension adjacent the inlet or inlets thereto and in advance of said abutment, the mouth of said extension at its point of junction with the main combustion chamber being flared, the flare being greater upon the leading edge of said mouth.

153. A rotary engine comprising a casing, a combustion chamber within the casing, a relatively rotatable rotor mounted therein, heads for the casing, means for admitting a motive agent to the combustion chamber, a valve controlling the admission of such agent and positioned at the entrance of such motive agent to said combustion chamber, an annular chamber to which a second motive agent may be supplied, and a plurality of passages leading from said annular chamber under the valve seat, whereby the second motive agent may be thoroughly intermixed with the first, and means for regulating the admission of the second motive agent through said passages.

154. A rotary engine comprising a casing, a combustion chamber within the casing, a relatively rotatable rotor mounted therein, means for admitting a motive agent to the combustion chamber, a valve controlling the admission to such agent, an annular chamber under the valve seat of said valve and to which a second motive agent may be supplied, and a plurality of passages leading from said annular chamber under the valve, whereby the second motive agent may be thoroughly intermixed with the first.

155. A rotary engine comprising a casing and a relatively rotatable rotor mounted therein, heads for said casing, means for securing them thereto, one or both of said heads having a portion extending into the casing and there contacting with the inner surface of said casing, and an expandible ring packing to provide a tight fit between that portion of the head or heads that contacts with the inner face of the casing.

156. A rotary engine comprising a casing, a rotor therein, an abutment, a main combustion or working chamber defined by said

parts and a narrow ignition chamber in said casing extending outwardly therein, the combustion or working chamber being of minimum extent when first placed in combination with the ignition chamber.

157. A rotary engine comprising in combination, a casing, a rotor mounted therein and having two spaced casing contacting portions and an admission port in the casing and controlled by the rotor, and a casing or contacting portion of the rotor exceeding in size said admission port.

158. A rotary engine comprising a casing, a shaft having a rotor thereon and mounted for relative rotation with respect to said casing, heads for said casing, said heads each having a tapering portion extending into recessed portions of the rotor, said tapering portions being threaded for movement axially of the shaft to take up wear.

159. A rotary engine comprising a casing, a rotor mounted for relative rotation therein, heads for said casing, an abutment mounted for movement in said casing and adapted to contact with said heads and recessed to permit exhaust therethrough, means for moving said abutment toward said rotor, and means for taking up wear between said head and heads and the contacting portion or portions of the abutment.

160. A rotary engine comprising a casing, a shaft having a rotor thereon and mounted for relative rotation with respect to said casing, one or more abutments within said casing and contacting with the rotor and having bodily movement toward and from the rotor, heads for said casing, both of said heads having a frusto-conical portion thereon surrounding the shaft and extending into the rotor, whereby the rotor may be centered with respect to said abutment.

161. A rotary engine comprising a casing, a shaft having a rotor thereon and mounted for relative rotation with respect to said casing, said rotor being shaped and mounted to contact with said casing, one or more abutments within said casing and contacting with the rotor, heads for said casing, both of said heads having a frusto-conical portion thereon surrounding the shaft and extending into the rotor, whereby the rotor may be centered with respect to said abutments.

162. A rotary engine comprising a casing, a shaft having a rotor thereon and mounted for relative rotation with respect to the casing, said rotor being shaped to contact with the casing at two spaced points, one or more abutments within said casing and contacting with the rotor heads for said casing, both of said heads having a frusto-conical portion thereon surrounding the shaft and extending into the rotor, whereby the rotor may be centered with respect to said abutments.

163. A rotary engine comprising a casing

and a relatively rotatable rotor mounted therein, heads for said casing, a channel being formed between one or both heads and the adjacent face or faces of the rotor for the reception of a lubricant, and means for supplying such lubricant thereto.

164. A rotary engine comprising a casing, a shaft carrying a relatively rotatable rotor within said casing, heads for said casing, an annular pocket surrounding said shaft being provided between one or both heads and the adjacent face or faces of said rotor for the reception of lubricant, and means for introducing the lubricant thereto.

165. A rotary engine comprising a casing, a shaft having a rotatable rotor mounted thereon and positioned within the casing, heads for said casing, one or both heads having a portion extending into the casing and acting as a bearing, and means for introducing a lubricant directly between such bearing portion and the side or sides of the rotor.

166. A rotary engine comprising a casing and a relative rotatable rotor therein, heads for said casing, means for securing said heads thereto, the heads and rotor having one a tapering part and the other a recessed part into which the tapering part extends, and a packing interposed between one or both of said heads and said casing.

167. A rotary engine comprising a casing and a relatively rotatable rotor mounted therein, heads for said casing, means for securing them thereto, one or both of said heads having a bearing portion separate therefrom and engaging the rotor, means for securing said bearing portion or portions to said head or heads, and a packing interposed between said bearing or bearings and said head or heads but exterior to the heads.

168. A rotary engine comprising a casing and a relatively rotatable rotor mounted therein, heads for said casing, means for securing them thereto, one or both of said heads having a portion extending into said casing and contacting with the inner surface of said casing, and a spring packing to provide a tight fit between that portion of the head or heads that so contacts with said inner face of the casing.

169. A rotary engine comprising a casing, a rotor therein and an abutment forming a main combustion or working chamber, and an ignition chamber, the casing contacting portion of the rotor being shaped so as to permit a minimum extension of the ignited motive fluid upon its admission to the main combustion or working chamber.

170. A rotary engine comprising a casing, a rotor therein, an abutment, a main combustion or working chamber defined by said parts and an ignition chamber in the said casing, the combustion or working chamber

being of minimum extent when first placed in communication with the ignition chamber.

171. A rotary engine comprising a casing and a relatively rotatable rotor mounted therein, heads for said casing, means for admitting the motive agent or agents to the combustion chamber, a valve for controlling such admission, mechanical means for periodically opening said valve, and a cam having a face constructed as an element of a cone to control the elevation of the valve, its time of opening and closing and length of opening through all gradations of adjustment.

172. A rotary engine comprising a casing, a combustion chamber within the casing, a relatively rotatable rotor mounted in said casing, heads for said casing, means for admitting a motive agent to the combustion chamber, a valve controlling the admission of such agent and positioned at the entrance of said motive agent to the combustion chamber and annular chamber to which a second motive agent may be supplied, and a plurality of passages leading from said annular chamber under the valve seat, whereby the second motive agent may be thoroughly intermixed with the first.

173. A rotary engine comprising in combination a casing, a rotor therein contacting with the casing, an admission port in the casing and controlled by the rotor, and a pivoted abutment co-acting with the rotor, the casing contacting part of the rotor exceeding in size said admission port.

174. A rotary engine comprising a casing and a relatively rotatable rotor mounted therein, heads for said casing, said rotor having one or more portions of its peripheral surface adapted to contact with the inner surface of the casing, a port or ports for introducing a motive agent or agents through the casing into operative relation to the rotor, a valve or valves for controlling the admission of such motive agent or agents, and means for opening said valve or valves prior to the closing by the rotor of the port or ports in the casing, whereby the motive agent is thus introduced into the chamber and whereby the chamber may be scavenged.

175. A rotary engine comprising a casing and a relatively rotatable rotor mounted therein, heads for said casing, said rotor having one or more portions of its peripheral surface adapted to contact with the inner surface of the casing, means for introducing a motive agent or agents through the casing into operative relation to the rotor, a valve or valves for controlling the admission of such motive agent or agents, and means for opening said valve or valves prior to the formation of a chamber or chambers between the peripheral surface of

the rotor and that portion of the casing through which the motive agent or agents are interposed whereby the motive agent is thus introduced into the chamber and whereby the chamber may be scavenged.

70

176. A rotary engine comprising a casing and a relatively rotatable rotor mounted therein, heads for said casing, said rotor having one or more portions of its peripheral surface adapted to contact with the inner surface of the casing, and being provided with a passage or passages for the introduction of a motive agent therethrough into the casing, and means for admitting a motive agent or agents through said passage or passages just prior to their closing by the rotor, whereby said passage or passages in the rotor may be used for scavenging.

80

177. A rotary engine comprising a casing and a relatively rotatable rotor mounted therein, heads for said casing, said rotor being adapted to coöperate with the casing to form a chamber for the reception of a motive force, said rotor having one or more passages therein for the introduction of a motive agent or agents into the chamber, and means for admitting a motive agent or agents through said passage or passages into the casing just prior to the admission of such agent or agents into said chamber.

95

178. A rotary engine comprising a casing and a relatively rotatable rotor mounted therein, heads for said casing, an abutment or abutments mounted in said casing and adapted to contact with the rotor, said rotor having a passage or passages therein for the admission of a motive agent or agents, and means for admitting such agent or agents prior to the closing of the mouth of such passage or passages by the abutment or abutments.

100

179. A rotary engine comprising a casing, a shaft having a rotor thereon and positioned within said casing, a cam, one or more movable abutments and operative connections between said cam and said abutment or abutments, said cam being shaped to vary the pressure of the engagement of said abutment or abutments with their co-operating part but maintaining engagement with such part.

110

180. A rotary engine comprising a casing and a relatively rotatable rotor mounted therein, heads for said casing, one or more abutments mounted for pivotal movement in said casing toward and from the center of rotation of the rotor, spring adjustable means connected with the abutment or abutments between the pivotal point thereof and its active portion to draw said abutment or abutments radially inward and means to introduce a motive agent to the rear of said abutment or abutments for forcing the same inward.

120

181. A rotary engine comprising a casing

130

and a relatively rotatable rotor mounted therein, heads for said casing, one or more abutments mounted for pivotal movement in said casing toward and from the center of rotation of the rotor, adjustable yielding means connected with the abutment or abutments between the pivotal point thereof and its active portion to draw said abutment or abutments radially inward and means for leading a motive agent to a part of the abutment or abutments in the rear of the active face or faces thereof for forcing said abutment or abutments inward.

182. A rotary engine comprising a casing and a relatively rotatable rotor mounted therein, heads for said casing, one or more abutments mounted for pivotal movement in said casing toward and from the center of rotation of the rotor, yielding means having substantially uniform tension and connected with the abutment or abutments between the pivotal point thereof and its active portion to move said abutment or abutments radially inward and means for adjusting the tension of said yielding means, and means for leading a motive agent to a part of the abutment or abutments in the rear of the active face or faces thereof for forcing said abutment or abutments inward.

183. A rotary engine comprising a casing and a relatively rotatable rotor mounted therein, heads for said casing, one or more abutments mounted for pivotal movement in said casing toward and from the center of rotation of the rotor and adapted to contact with the peripheral surface of the rotor, means operatively engaging the abutment or abutments between the pivotal point thereof and the active portion to draw such abutment or abutments radially inward, means to adjust the tension of said means and means to introduce a motive agent to the rear of said abutment or abutments, for forcing the same inward.

184. A rotary engine comprising a casing, a shaft having a rotor thereon and positioned within said casing, a cam also mounted upon said shaft, heads for said casing, one or more abutments in said casing movable toward and from the center of rotation of the rotor and adapted constantly to contact therewith, and operative connections from said cam to said abutment or abutments, whereby said abutment or abutments may be drawn radially inward and means to adjust the tension of said means.

185. A rotary engine comprising a casing and a relatively rotatable rotor mounted therein, heads for said casing, one or more abutments mounted for pivotal movement in said casing toward and from the center of rotation of the rotor and adapted to contact with the peripheral surface of the rotor, a cam to move said abutment or abutments radially inward and adjustable cushioning

means between said abutment or abutments and said cam.

186. A rotary engine comprising a casing, a shaft having a rotor mounted thereon and positioned within said casing, a cam mounted about said shaft, heads for said casing, one or more abutments mounted for pivotal movement toward and from the center of rotation of the rotor and adapted to contact with the peripheral surface thereof, and operative connections between said cam and said abutment or abutments forward of the pivotal point thereof for moving the same radially inward and adjustable cushioning means between said abutment or abutments and said casing, whereby uniform pressure is maintained.

187. A rotary engine comprising a casing, a shaft having a rotor thereon and positioned within said casing, an internal cam mounted about said shaft, heads for said casing, one or more abutments mounted in said casing and movable toward and from the center of rotation of said rotor and adapted to contact with the peripheral surface thereof, connections between said cam and said abutment or abutments to direct the latter radially inward and adjustable cushioning means between the abutment or abutments and said cam whereby uniform pressure is maintained.

188. A rotary engine comprising a casing, a shaft having a rotor mounted thereon and positioned within said casing, a cam mounted about said shaft, heads for said casing, one or more abutments mounted in said casing and movable toward and from the center of rotation of said rotor and adapted to contact with the peripheral surface thereof, and connections between said cam and said abutment or abutments to draw said abutment or abutments radially inward, said connections maintaining said abutment or abutments in contact with the peripheral surface of the rotor with a uniform pressure and adjustable connections between said cam and said abutment or abutments.

189. A rotary engine comprising a casing, a shaft having a rotor thereon and positioned within said casing, a cam mounted about said shaft, heads for said casing, one or more abutments mounted in said casing and movable toward said shaft and adapted to contact with the peripheral surface of the rotor, and connections from said cam to said abutment or abutments to move them, said cam being shaped to vary the pressure of the engagement of said abutment or abutments with the peripheral surface of the rotor.

190. A rotary engine comprising a shaft having a rotor thereon positioned within said casing, a cam mounted about said shaft, heads for said casing, and one or more abutments mounted in said casing and movable

toward and from said shaft to contact with the peripheral surface of the rotor, said cam being circumferentially adjustable with respect to the rotor.

5 191. A rotary engine comprising a casing, a shaft having a rotor thereon and positioned within said casing, a cam mounted about said shaft, heads for said casing, an abutment or abutments positioned for cooperation with said rotor and casing, and connections from said cam to said abutment or abutments to move them into operative position, said cam being shaped to vary the pressure of the abutment or abutments with 10 that part wherewith it contacts when in operative position.

192. A rotary engine comprising a casing, a shaft having a rotor thereon and positioned within said casing, a cam mounted 20 about said shaft, heads for said casing, an abutment or abutments positioned for cooperation with said rotor and casing, connections from said cam to said abutment or abutments to move them into operative position, said cam being shaped to vary the pressure of the abutment or abutments with 25 that part wherewith it contacts when in operative position, and means circumferentially to adjust said cam with respect to 30 the rotor.

193. A rotary engine comprising a casing, a shaft having a rotor thereon and mounted for relative rotation with respect to said casing, heads for said casing having tapering portions extending into correspondingly recessed portions of the rotor, means to admit a motive agent through said tapering portions and through said rotor, and means to move said head or heads axially of the 40 shaft to take up wear.

194. A rotary engine comprising a relatively rotatable rotor mounted therein, heads for said casing, means for admitting a motive agent or agents to the combustion 45 chamber, a valve controlling such admission, mechanical means for periodically opening said valve and a tooth for regulating the period of lift of the valve.

195. A rotary engine comprising a casing 50 and a relatively rotatable rotor mounted thereon, heads for said casing, a plurality of chambers being simultaneously formed within said casing for the reception of a motive agent or agents, and a plurality of 55 abutments, said abutments being adapted respectively to form a portion of each of said chambers, and yielding means to reverse the position of said abutments.

196. A reversible rotary engine comprising 60 a casing and a relatively rotatable rotor mounted therein, heads for said casing, a plurality of chambers being simultaneously formed within said casing for the reception of a motive agent or agents, means for introducing a motive agent or agents for di-

rect action of the engine, means for introducing a motive agent or agents for operating the engine in the reverse direction, abutments mounted for coöperation with the rotor and casing, means for cutting off the 70 supply of the motive agent or agents into the cylinder and into the casing, and adjustable means for reversing the position of the abutments.

197. An internal combustion engine comprising a casing and a relatively rotatable 75 rotor mounted therein, heads for said casing, a plurality of chambers being simultaneously formed within said casing for the reception of a motive agent or agents, one 80 or more abutments mounted for coöperation with said rotor and said casing, there being passages for introducing the motive agent or agents for expansion, for direct operation of the engine, and a passage or passages 85 for introducing an agent or agents for expansion, for the reverse operation of the engine, and means for admitting the agent or agents through certain passage or passages and cutting it off from the other passage or passages and for reversing the engine. 90

198. A rotary engine comprising a casing, a shaft having a rotor thereon and mounted for relative rotation with respect to said 95 casing, heads for said casing, one of said parts, namely, said head or heads and said rotor, having a tapering portion extending into the other, means to admit a motive agent directly through said tapering portion 100 into the rotor, and means to move the part or parts having said tapering portion axially of the shaft to take up wear.

199. A rotary engine comprising a casing, a shaft having a rotor thereon and positioned within said casing for relative rotation with respect thereto, heads for said casing, one of said parts, namely—a head or 105 said rotor, having a tapering portion surrounding the shaft and extending into a 110 correspondingly recessed portion of the other, and provisions for introducing a motive agent or agents into the rotor where said tapering and recessed portions are juxtaposed.

200. A rotary engine comprising a casing, a shaft having a rotor thereon and mounted for relative rotation with respect to said casing, heads for said casing, one of said parts, namely, a head or heads and said 120 rotor, having a tapering portion surrounding the shaft and extending in the other, and said tapering portion or portions having ports at opposite sides of the shaft, so as to balance the introduction of motive fluid. 125

201. A rotary engine comprising a casing, a shaft having a rotor thereon and mounted for relative rotation with respect to said casing, heads for said casing, both of said heads having a tapering portion surround- 130

ing the shaft and extending into the rotor, and both of said portions having ports at opposite sides of the shaft, whereby the introduction of motive fluid through said 5 tapering portions is balanced.

202. A rotary engine comprising a casing and a relatively rotatable rotor mounted therein, heads for said casing, one or more abutments mounted in said casing and 10 adapted to engage the peripheral surface of said rotor, there being a chamber between the face of the abutment and the casing for cushioning the outward movement of said abutment or abutments, said chamber being periodically directly open to the 15 exhaust.

203. A rotary engine comprising a casing and a relatively rotatable rotor mounted therein, heads for said casing, one or more 20 abutments mounted in said casing and adapted to engage the peripheral surface of said rotor, means for cushioning the outward movement of said abutment or abutments, and means for regulating such cushioning action, said abutment or abutments, being recessed for passage of the exhaust.

204. A rotary engine comprising a casing and a relatively rotatable rotor mounted therein, heads for said casing, said rotor 30 being adapted to coöperate with the casing to form a chamber for the reception of a motive force, said rotor having one or more passages therein for the introduction of a motive agent or agents into the chamber, 35 and means for admitting a motive agent or agents through said passage or passages into the casing to scavenge the latter.

205. A rotary engine comprising a casing and a relatively rotatable rotor mounted 40 therein, heads for said casing, one or more chambers being formed within said casing for the reception of a motive agent or agents, one or more abutments movable toward and from said rotor, said abutment or abutments 45 being adapted respectively to form a portion of said chamber or chambers and being recessed to permit the motive agent to exhaust therethrough, and adjustable means to reverse the position of said abutment or abutments.

206. In a device of the character described the combination of a casing having a chamber, a rotary piston therein, a spring pressed abutment and a cam for mechanically operating 50 said abutment and a co-acting compression chamber in the rear of the abutment, said compression chamber being periodically open to said casing chamber.

207. In a device of the character described, 60 the combination of a casing having a cylindrical chamber, a rotary piston therein; a pivoted blade; a spring pressed pivoted abutment and mechanical means for operating said abutment, and a co-acting compression chamber in the rear of the abut- 65

ment periodically open to said cylindrical chamber.

208. In a device of the character described, the combination of a casing having a cylindrical chamber, a rotary piston therein; a 70 pivoted blade; a spring pressed, pivoted abutment recessed for the passage of the exhaust therethrough; and a cam for mechanically operating said abutment and a co-acting compression chamber in the rear of the 75 abutment.

209. In a device of the character described, the combination of a casing, a rotary piston therein, an adjustable spring pressed abutment, a cam for operating said abutment, 80 and a compression chamber in the rear of the abutment constructed and arranged to be periodically opened to the exhaust.

210. An internal combustion engine comprising a casing, a piston therein, an ignition and a sparking plug therefor positioned adjacent the portion of the chamber that is 85 constructed and arranged to receive greatest volume of the mixture therein.

211. A rotary power transforming device 90 comprising in combination a casing, a rotor, a head or heads for the casing and a movable abutment or abutments, the head or heads and rotor having adjacent tapering faces, packing interposed between said 95 tapering faces and means to admit motive agent through a head into the rotor.

212. A rotary power transforming device comprising in combination a casing, a rotor, a head or heads for the casing and a movable abutment or abutments, the head or heads having a tapering surface, a packing interposed between said surface and the part received therein and means for admitting motive agent through the casing 105 and through the rotor.

213. A rotary power transforming device comprising in combination a casing, a rotor, a head or heads for said casing, and a movable abutment or abutments having an opening therethrough for the passage of the exhaust, the adjacent faces of a pair of said parts being tapered and packing interposed between such tapered faces.

214. A rotary engine comprising in combination a rotor therein and a head or heads for said casing, one or both of said heads and said rotor having ports therein for the motive agent or agents and packing interposed between and about the said ports in 115 the head or heads and said rotor.

215. A rotary engine comprising a casing, a shaft having a rotor thereon and mounted for relative rotation with respect to the casing, and a head or heads for said casing, one or both of said heads having a frusto conical portion thereon surrounding said shaft and extending into said rotor and provided with ports at opposite sides of said shaft, whereby the introduction of motive fluid is balanced.

216. A rotary engine comprising a casing, a rotor therein, an abutment adapted to engage the rotor, a chamber between the abutment and casing and independent of the admission port to admit motive fluid to the abutment to force it into engagement with the rotor prior to the admission of motive fluid to the working face of the rotor, means to vary the pressure of the fluid in said chamber, and valve means carried by the

5 abutment to admit fluid pressure to the rear of the latter.

In testimony whereof, I have signed my name to this specification, in the presence of two subscribing witnesses.

WILLIAM NICHOLS MEARNS.
